MULTIPLE CONTROL APPARATUS

Lester E. Spray, Wilkinsburg, Pa., assignor to The
Union Switch & Signal Company, Swissvale,
Pa., a corporation of Pennsylvania

Application September 5, 1931, Serial No. 561,422
Renewed April 1, 1937

80 Claims. (Cl. 246—134)

My invention relates to multiple control apparatus, and is particularly adapted for, though not limited to, the control of railway track switches and signals in a railway switching or interlocking layout.

One feature of my invention is the provision of apparatus comprising circuit controllers each which has a plurality of positions for controlling a plurality of partly inter-inclusive groups of devices. Another feature of my invention is the provision of interlocking control without the use of mechanically interlocked levers.

More particularly, the principal object of my invention is the provision of an improved system of route interlocking, in which the track switches of a railway track layout are controlled by means of route buttons or freely operable levers, and in which the signals are cleared automatically in response to the operation of the track switches by the route buttons, errors in manipulation being guarded against by the provision of suitably interlocked circuits for controlling the switches and signals, in lieu of interlocking between levers as generally employed heretofore. The apparatus disclosed herein is an improvement upon that disclosed in my co-pending application, Serial No. 323,286, filed December 3, 1928, for Multiple control apparatus, and also upon that disclosed in an application, Serial No. 416,061, filed December 23, 1929, by H. A. Thompson, for Multiple control apparatus.

In one form of the apparatus of my prior application above referred to, I provide a control board having thereon a miniature diagram of the track layout with rotary buttons mounted thereon at points corresponding to the ends of the routes, and any desired route may be established by operating the two buttons which identify its opposite ends. In the present invention, a generally similar control board is employed but its operation is simplified by the provision of route buttons each of which may be rotated to a plurality of positions, one for the destination or exit end of each route having its entrance end identified by the location of the operated button on the diagram, and the desired route is selected by pressing the entrance button to momentarily close a push button exit contact in the selected position. Each button thus constitutes a master control element which identifies the entrance end of the desired route, and the exit buttons are auxiliary control elements operated to complete the identification of the desired route, by a distinctive manipulation of the entrance but-

Another object of the present invention is to further facilitate manipulation by the provision of self-restoring buttons, and by establishing the routes by the operation of route relays controlled by the buttons which so function that the routes are held established by the relays and cannot be interfered with by the operation of conflicting route buttons. I also provide arrangements whereby a train moving over an established route cancels it automatically. This is accomplished by releasing the route relays involved when the train enters the first track section of a route. Prior to clearing the signal for a route, the establishment of a route prevents the establishment of a conflicting route because of the provision of interlocked circuits for the route relays, while after the train enters a route the establishment of a conflicting route is prevented by the operation of the switch locking controlled by the signals, which holds each switch of the route locked in the required position until the train successively occupies and vacates the corresponding track section.

A feature of this form of my invention is the provision of means for cancelling a route manually by a different manipulation of the entrance button. In an alternative form, the rotary entrance buttons may be of the "stay-where-put" type, in which case the routes are held established by relays held energized by the entrance buttons only, so the manual cancellation may be effected by merely restoring the entrance button to normal.

Still another feature of my invention resides in the provision for the control of "call-on" signals in a system of this character by an additional manipulation of the entrance button after a route has been established, an independent call-on button, as used heretofore, not being required.

The apparatus of the present invention is distinguished from that of my prior application in other respects, in that the pair of route devices identifying each route controls all of the track switches for that route, and the track switches are allowed to remain in their last operated positions after a route is cancelled, instead of being restored to their normal positions. Thus, although the routes are cancelled automatically, the track switches are operated only in response to manual operation of the route buttons, as heretofore. Furthermore, the circuits as disclosed herein include a route circuit network supplementing the circuits which directly control the signals, which safeguard the operation by check-

ing the correspondence of each track switch of the route with the relays controlled by the route buttons before a signal can be cleared. The circuits also include the control of the signals by the time locking relays controlled by opposing signals to safeguard the reversal of the traffic direction in an established route.

I will describe two forms of apparatus embodying my invention, and will then point out the novel features thereof in claims.

In the accompanying drawings, Figs. 1 to 13, inclusive, are diagrammatic views showing the component parts of one form of apparatus embodying my invention. A second form of apparatus embodying my invention is shown by Figs. 1, 2, 6, 7, 8, 9, 11, 14, 15, 16 and 17, inclusive all of which are diagrammatic views.

Similar reference characters refer to similar parts in each of the views.

Referring first to Fig. 1, this drawing shows a track layout comprising a plurality of track sections interconnected by track switches to form different traffic routes. As illustrated, the layout consists of a stretch of double track railway, tracks *aa* and *bb* of which are interconnected through a crossover *ee* with which they are respectively joined by switches *H*² and *H*^{2a}, and are likewise interconnected by a second crossover *ff* with which they are respectively joined by switches *H*³ and *H*^{3a}. Tracks *aa* and *bb* are also respectively joined to passing sidings *cc* and *dd* by switches *H*⁴ and *H*¹. The reference characters *f* and *f*^a designate the rails of track *aa*, and the reference characters *2* and *2*^a designate the rails of track *bb*.

These rails are divided by insulated joints *3* to form a plurality of track sections *a*—*A*, *A*—*ii*, *ii*—*ji*, *ji*—*E*, *B*—*mm*, *mm*—*G*, *G*—*D* and *D*—*d*. Each of these track sections is supplied with current by a battery *4* connected across the rails adjacent one end of the section. A track relay designated by the reference character *T*, with a distinguishing exponent, is connected across the rails adjacent the opposite end of each track section.

Reference character *S*, with distinguishing exponents, designates signals which are placed at the entrances to the different routes adjacent the points *A*, *B*, *C*, *D*, *E* and *F*, respectively, and which, as here shown, are of the semaphore type. Signals *S*^{1a}, *S*^{1b} and *S*^{1c} are mounted on a common mast *10*, and signals *S*^{4a}, *S*^{4b} and *S*^{4c} are mounted on a common mast *9*. Signals *S*^{1a}, *S*^{1b}, *S*^{1c}, *S*² and *S*³ govern east bound traffic moves, that is, moves which are made over the stretch of track from left to right as shown in the drawings, and signals *S*^{4a}, *S*^{4b}, *S*^{4c}, *S*⁵ and *S*⁶ govern westbound traffic moves, that is, moves which are made over the stretch of track from right to left as shown in the drawings.

Between the group of eastbound signals and the group of westbound signals, eleven different routes may be established according to the positions of the various switches. Over each of these routes, traffic can proceed in either direction, that is, from west to east, or from east to west, as controlled by a signal for each direction of traffic over each route, respectively.

The arrangements of the switches for these various routes are as given in the following table:

Route 1.—A to E, switches *H*², *H*³ and *H*⁴ normal.

Route 2.—A to F, switches *H*² and *H*³ normal, and *H*⁴ reversed.

Route 3.—A to D, switches *H*² and *H*^{2a} reversed, and *H*^{3a} normal.

Route 4.—A to G to E, switches *H*², *H*^{2a}, *H*^{3a} and *H*³ reversed, and *H*⁴ normal.

Route 5.—A to G to F, switches *H*², *H*^{2a}, *H*^{3a}, *H*³ and *H*⁴ reversed. 5

Route 6.—B to D, switches *H*¹, *H*^{2a}, and *H*^{3a} normal.

Route 7.—B to E, switches *H*¹, *H*^{2a}, and *H*⁴ normal, and *H*^{3a} and *H*³ reversed. 10

Route 8.—B to F, switches *H*¹ and *H*^{2a} normal, and *H*³ and *H*⁴ reversed.

Route 9.—C to D, switch *H*¹ reversed, and switches *H*^{2a} and *H*^{3a} normal.

Route 10.—C to E, switches *H*¹, *H*^{3a} and *H*³ re- 15 versed, and *H*^{2a} and *H*⁴ normal.

Route 11.—C to F, switches *H*¹, *H*^{3a}, *H*³ and *H*⁴ reversed, and *H*^{2a} normal. 10

Each track section in which a switch is located 20 will be referred to hereinafter as a detector section. Track sections *a*—*A* and *D*—*d* in the rear of signals *S*¹ and *S*⁴, respectively, will be referred to as approach track sections.

Each switch *H* is operated by a motor design- 25 nated by the reference character *M* with an exponent corresponding with that of the reference character *H* for the switch. Each motor *M* comprises an armature *t*² and a field winding *13*. The motors *M*³ and *M*^{3a} for operating switches 30 *H*³ and *H*^{3a}, respectively, of crossover *ff*, are controlled in multiple by pole-changing contacts of a polarized relay *m*³, the control for which is shown in Fig. 11. The control of the motors for operating switches *H*² and *H*^{2a} of crossover *ee* is 35 similar to that for motors *M*³ and *M*^{3a}, and is therefore not shown in the drawings. Motor *M*⁴ for operating switch *H*⁴ is controlled by pole-changing contacts of polarized relay *m*⁴. The control for the motor of switch *H*¹ is similar to that for motor *M*⁴, and is therefore omitted from the drawings. 40

Included in the control circuits for each motor *M*, are four asymmetric units *i*¹, *i*², *i*³ and *i*⁴. Each of these units is so constructed that it will permit the flow in only one direction of sufficient current to operate the motor, for example, unit *i*⁴, in the circuit for motor *M*⁴, permits current of sufficient magnitude to operate motor *M*⁴ to flow away from contact *16* of a circuit controller *y*⁴, but not toward contact *16*. Each of the units *i* 45 may be similar to those disclosed and claimed in Letters Patent of the United States, No. 1,640,335, granted to L. O. Grondahl, August 23, 1927. 50

Operated in conjunction with each switch *H*, 55 is a circuit controller designated by the reference character *y* with an exponent corresponding with that of the reference character *H* for the switch. Contacts *14*, operated by these circuit controllers and included in the control circuits for switch motors *M*, are closed at all times except while the respective switches are in their normal position. Contacts *16*, also operated by these circuit controllers, and which are also included in the control circuits for switch motors *M*, are closed 60 at all times except while the respective switches are in the reverse position. 65

The circuit controller *y*⁴ for switch *H*⁴ is provided with pole-changing contact arms *18* and *19*. A polarized relay, designated by the reference character *m*⁴, for controlling operations of switch *H*⁴ to the normal or the reverse position according as this relay is energized in the normal or the reverse direction, is provided with polar contacts *17*^m⁴ and *23*^m⁴. A circuit for con- 70 75

trolling a polarized switch indication relay h^4 is so controlled by contacts 17^{m^4} and 20^{m^4} and by contact arms 18 and 19 of circuit controller y^4 that the contacts of indication relay h^4 will become closed in the normal direction when switch H^4 occupies its normal position while its control relay m^4 is energized in the normal direction, and the contacts of indication relay h^4 will become closed in the reverse direction when switch H^4 occupies its reverse position while relay m^4 is energized in the reverse direction. The control of relay h^1 by a similar circuit controller y^1 and polarized relay m^1 for switch H^1 is similar to that of relay h^4 , and is therefore not shown in the drawings.

Switch circuit controller y^3 is provided with contact arms 23 and 24 , and circuit controller y^{3a} is provided with contact arms 22 , 25 , 26 and 27 . Contacts 21^{m^3} and 28^{m^3} of a polarized relay m^3 , which controls operations of switches H^3 and H^{3a} , are so associated with contacts 22 , 25 , 26 and 27 of circuit controller y^{3a} and contact arms 23 and 24 of circuit controller y^3 in the control of a polarized switch indication relay h^3 as to cause the polar contacts of relay h^3 to be closed in the normal direction when switches H^3 and H^{3a} occupy their normal position while relay m^3 is energized in the normal direction, and to cause the polar contacts of relay h^3 to be closed in the reverse direction when switches H^3 and H^{3a} are in their reverse position while relay m^3 is energized in the reverse direction. The control of polarized switch indication relay h^2 by switches H^2 and H^{2a} and relay m^2 is similar to that of relay h^3 by switches H^3 and H^{3a} and relay m^3 , and is therefore not shown in the drawings.

Each of the signals shown in the drawings operates a circuit controller having contacts which are closed when and only when their signal is indicating "stop." Such contacts are shown adjacent the signal diagrams in Fig. 1, and are designated by the reference numbers 29 , 30 , 31 and 36 , respectively. Similar contacts are shown adjacent the diagrams for signals S^1 and S^4 in Figs. 13 and 17.

Contacts 31 , 30 and 29 , shown in Fig. 1 adjacent the diagrams for signals S^1 , are operated by signals S^{1a} , S^{1b} and S^{1c} , respectively, and are included in the control circuit for an approach locking relay designated by the reference character Ps^1 . Similar contacts 31 , 30 and 29 , shown adjacent the diagrams for signals S^4 in Fig. 1, are operated by signals S^{4a} , S^{4b} and S^{4c} , respectively, and are included in the control circuit for a second approach locking relay designated by the reference character Ps^4 . Similar contacts 36 , operated by the signals S^2 , S^3 , S^5 and S^6 , respectively, are included in the control circuits for stick locking relays Q^{S^2} , Q^{S^3} , Q^{S^5} and Q^{S^6} , respectively.

Approach locking relay Ps^1 becomes deenergized when the arm of any of the signals S^1 leaves its stop position. Relay Ps^4 is similarly controlled by signals S^4 . Each of these approach locking relays is also so controlled that, while a respective approach track relay is deenergized, the approach locking relay can again become energized only through a back contact of the track relay for an adjacent detector track section, or through a time releasing device contact which will become closed only upon the lapse of a measured interval of time after the beginning of the operation of the releasing device. These releasing devices may be of the well-known clock-

work type, and are designated by the reference letter J with distinguishing exponents.

Stick locking relay Q^{S^2} becomes deenergized when the arm of signal S^2 leaves its stop position. Relay Q^{S^2} can then again become energized only on the deenergization of detector track section relay T^5 , or upon the closing of contact 39 of a time relay N^{S^2} when signal S^2 is indicating "stop". As here shown, time relay N^{S^2} is of the thermal type, comprising a heater winding 40 , which, upon the lapse of a period of time after it has become energized, causes its contact 39 to close. Relays Q^{S^3} , Q^{S^5} and Q^{S^6} are controlled similarly to relay Q^{S^2} .

Approach and stick locking relays P and Q , when deenergized, prevent the operation of each switch in the routes governed by the signals associated in the control of these relays, thus enforcing, after a signal has been returned to its stop position, the lapse of a measured time interval before the switches in the route governed by the signal can again be operated.

In each of the drawings, the contacts operated by the various relays or by the time releases J or by other control devices which will be hereinafter described are identified by numbers, such numbers having distinguishing exponents when such contacts are not shown adjacent the respective relay or release or other device by which they are operated. The exponent for each of these contact numbers comprises the reference character and exponent for the respective relay, release, or other device. For example, the exponent T^5 for contact 37^{T^5} , shown in the circuit for relay Q^{S^2} in Fig. 1, comprises the reference character T and its exponent 5 for track relay T^5 which operates contact 37^{T^5} . Similarly, exponent m^4 for contact 11^{m^4} , in the operating circuit for motor M^4 , comprises reference character m and its exponent 4 for switch control relay m^4 which operates contact 11^{m^4} .

In Fig. 2 is shown a combined track diagram and operating board on which manually operable devices, designated by the reference character K with distinguishing exponents, are disposed adjacent points A , B , C , D , E and F , respectively. Each of the points A , B , C represents a point of traffic entrance and each of the points D , E , F represents a point of traffic exit for movements from left to right over a given group of routes in a plurality of partly inter-inclusive groups of routes, respectively. Likewise, each of the points D , E , F represents a point of traffic entrance and each of the points A , B , C represents a point of traffic exit for movements from right to left over the same group of routes.

As here indicated, each of the devices K is of a rotatable push button type, capable of rotation from a normal position n into each of various positions corresponding to the exit points for each of the routes, respectively, in a group of routes which have a common traffic entrance point corresponding to the location of the device K . Each of these positions of each device K is designated by the reference character r with an exponent indicative of the exit end of the particular route with which it is associated. For example, position r^{1E} of device K^1 is associated with the exit end E of route 1 extending from point A adjacent signals S^1 to point E . Also, position r^{1GF} of device K^1 is associated with the exit end F of route 5 extending from point A adjacent signals S^1 over switches H^2 , H^{2a} reversed to point G , and from that point over switches H^{3a} , H^3 and H^4 reversed, to point F .

Also, similarly, position r^{5B} of device K^5 is associated with the exit end B of the route extending from point E adjacent signal S^5 over switches H^3 and H^{3a} reversed, to point B .

- 5 In addition to the positions r associated with the various routes, device K^1 has a position r^{1S} , which is associated with the control of the "call-on" indication of signal S^{1c} . Device K^4 has a similar position r^{4S} which is associated with the control of the call-on indication of signal S^{4c} .

Each of the devices K , when in any of its positions r , can be deflected manually from its plane of rotation to close a contact of an auxiliary route control device which is shown in Fig. 3 and which is designated by the reference number 5 with an exponent which is the same as the exponent for the associated position of the device K . Each contact 5 serves as an exit control element for the corresponding route, 15 there being one such contact for the exit end of each route which the device K governs. Each of the devices K , when in its normal position n , can be similarly deflected to open a contact which is designated by the reference number 6 20 with a corresponding exponent.

Each device K is also equipped with a master route control contact such, for example, as contact 7^{K1} of device K^1 , shown in Fig. 3. This contact comprises a contact arm 7 which connects 25 with a segment 7^a when its device K is manually rotated to the right of its position n , and continues closed until the device K is returned to a point adjacent the position n . Devices K for the opposite direction of traffic, such for example as K^4 , are equipped with similar contacts 30 7 which are closed when the device K is manually rotated to the left of its position n . Each contact 7 serves as an entrance control element for each route which the corresponding device 35 K governs.

Each entrance contact 7 and the corresponding exit contact 5 for a given route will, upon becoming closed, if certain other conditions are right, cause the switches of the route to be arranged in the positions required for the route, 40 and will cause a signal to be cleared for a given direction of traffic movement over the route after the switches have been arranged. In other words, the switches and signal for each route 45 are controlled jointly by the entrance control element and the exit control element for that particular route.

Each of the devices K^1 , K^2 and K^3 is arranged to be rotated to the right of its n position, for 50 governing eastbound traffic movements, as shown for device K^1 in Fig. 3. Each of the devices K^4 , K^5 and K^6 is arranged to be rotated to the left of its n position, for governing westbound traffic movements, as shown for device K^4 in Fig. 3a. If desired, however, devices K^1 , K^2 and K^3 can also be arranged for rotation to the left, for also controlling westbound traffic movements past points A , B and C , respectively. Devices K^4 , 60 K^5 and K^6 can similarly be arranged for rotation to the right, for also controlling eastbound traffic movements past points D , E and F , respectively.

Each of the devices K may be biased to its 70 normal position n by any suitable means such, for example, as a spring 8, shown in Figs. 3 and 3a, one end of which is attached to the device K and the other end of which is fixed to a stationary element p . These springs can, however, be omitted if desired, and the device K will

then be manually returnable to the normal position.

Adjacent each of the devices K is an indicator which is here shown as an indicator lamp e . These lamps are controlled as will be herein-after described.

For each entrance control element or master route contact 7, there is an entrance stick relay designated the master route relay and identified by the reference character W with a distinguishing exponent, as shown in Fig. 5, and for each exit control element or exit stick contact 5, there is an auxiliary route relay designated the auxiliary route relay and identified by the reference character g with a distinguishing exponent, as shown in Fig. 4. Each master route contact 7 of the devices K , upon becoming closed, causes its route relay W to become energized when certain other master route relays W are deenergized and when certain auxiliary route relays g are deenergized. Each auxiliary route relay g is energized by momentarily closing the corresponding contact 5, but can become energized only when a front contact of its associated master route relay W is closed. The relays W and g when energized control certain switch control relays X and R which govern relays m to operate the track switches as required to establish the corresponding route, and also control a signal control relay Y for clearing the signal for the route when established. After a device K has been operated to energize a pair of stick relays W and g , the device K may be restored to normal and the operated relays will be held energized over their stick circuits. These relays release automatically when a train passes the signal and enters the established route, but they may also be released manually to cancel an established route, by the momentary opening of the contact 6 of the associated device K .

To arrange for a traffic movement by a given route such, for example, as route 9 in the direction from D to C , the operator will rotate device K^4 toward the left and deflect it in its position r^{4C} . This operation of device K^4 closes contact 7^{K4} in the pick-up circuit for master route relay W^4 shown in Fig. 5, and also closes contact 5^{4C} . The consequent energization of relay W^4 , together with the closing of contact 5^{4C} , causes relay g^{4C} , shown in Fig. 4, to become energized. Relay W^4 then continues energized by a stick circuit until a train passes signals S^4 , deenergizing track relay T^7 , or until the operator deflects device K^4 in its n position, thereby opening its contact 6^{K4n} . Relay g^{4C} will continue energized by a stick circuit as long as relay W^4 continues energized, and if the operator does not energize relay g^{4B} . Relay g^{4C} , upon becoming energized, causes normal switch control relay X^2 , shown in Fig. 10, to become energized, and causes reverse switch control relay R^1 to become energized. Relay W^4 , upon becoming energized, causes normal switch control relay X^3 to become energized. Reverse switch control relay R^1 , upon becoming energized, causes a polarized switch control relay m^1 , shown in Fig. 11, to be energized by current of what I will term "reverse" polarity. Normal switch control relays X^2 and X^3 , upon becoming energized, cause polarized switch control relays m^2 and m^3 , also shown in Fig. 11, to become energized by current of what I will term "normal" polarity.

Relay m^1 , upon becoming energized in the reverse direction, causes switch H^1 to be operated to its reverse position. Relays m^2 and m^3 , upon

becoming energized in the normal direction, cause switches H^2 , H^{2a} , H^{3a} and H^3 to be moved to their normal positions, if they are not already in those positions. When switch H^1 is operated to its reverse position, polarized switch indication relay h^1 , shown in Fig. 1, becomes energized in the reverse direction. When switches H^2 , H^{2a} , H^{3a} and H^3 occupy their normal positions, relays h^2 and h^3 , respectively, are energized in the normal direction.

With the switches arranged for the route from D to C, a signal control relay Y^4 , shown in Fig. 12, becomes energized. Relay Y^4 , upon becoming energized, completes an operating circuit for signal S^{4b} , the arm of which then moves to its proceed position.

Relay W^4 and, in turn, relay g^{4c} will become deenergized when a train passes signals S^4 and causes relay T^7 to become deenergized. If, however, the operator should, before a train passes signals S^4 , desire to arrange a route which conflicts with the route from D to C, or when he desires to simply return the arm of signal S^{4b} to its stop position, he will deflect device K^4 in its n position, thereby opening contact 6^{K4n} in the stick circuit for relay W^4 , and will so cause relay W^4 , and in turn relay g^{4c} , to become deenergized. The arrangement of any other route can then be accomplished under given conditions by deflecting a corresponding device K in a corresponding position.

In Fig. 6, circuits are shown for signal call-on control relays Z^{S1} and Z^{S4} which are controlled by call-on contacts 5^{1s} and 5^{4s} , respectively, shown in Figs. 3 and 3a.

In Fig. 7, indicator lamps e are shown controlled by master route relays W .

In Fig. 8, route locking relays are shown, each of which is designated by the reference letter V with a distinguishing exponent including the letter e . These relays are controlled to prevent operation of the switches in corresponding routes when an approach or stick locking relay P or Q , respectively, for the eastbound direction of traffic is deenergized. Route locking relays, each of which is designated by the letter V with an exponent including the letter w are similarly controlled to prevent operation of the switches in corresponding routes when an approach or stick locking relay P or Q , respectively, for the westbound direction of traffic is deenergized.

Circuits are shown in Fig. 9 for signal stick relays. Each of these is designated by the letter L with an exponent to indicate the signals with which it is associated. Each of these stick relays is controlled by the approach locking relay P which is associated with the same signals, as well as by track relays T for all track sections over which the signals govern.

Fig. 10 shows the control circuits for normal and reverse switch control relays X and R , respectively, to which I have already referred.

Fig. 11 shows the controls for polarized switch control relays m to which I have also previously referred.

Circuits for signal control relays Y are shown in Fig. 12. These relays are provided merely to supply duplication of a portion of the signal control circuits shown in Fig. 13, and can therefore be omitted if desired. Complete interlocking control is provided by apparatus comprising my invention without the use of these relays Y .

Control circuits for all signals are shown in Fig. 13.

Having thus described, in general, the arrangement and location of the various parts included in the first form of apparatus embodying my invention, I will now proceed to explain the operation of this form of apparatus embodying my invention.

As shown in the drawings, all parts are in their normal condition, that is, each track section is clear; each control device K is in its normal position n ; the polar contacts of each switch control relay m are in their normal position; each track switch H is in its normal position; and each signal S is indicating "stop." Because switch H^4 is in its normal position, contact arms 18 and 19 of circuit controller y^4 connect with terminals 18^a and 19^a , respectively.

With the polar contacts of relay m^4 in their normal position, current is therefore supplied in the normal direction to relay h^4 by a circuit not shown in the drawings, through contact 17^{m4} closed in its normal position, contact 18^a-18 of circuit controller y^4 , winding of relay h^4 , and contact $19-19^a$ of circuit controller y^4 to terminal o of the same source of current. Relay h^4 is therefore energized in the normal direction, and hence its contacts are in the normal position.

On account of switches H^3 and H^{3a} being in their normal position, and on account of the polar contacts of switch control relay m^3 being in the normal position, polarized indication relay h^3 is energized in the normal direction by its circuit passing from terminal x , through contact 21^{m3} , contact 22^a-22 of circuit controller y^3a , contact 23^a-23 of circuit controller y^3 , winding of relay h^3 , contact $24-24^a$ of circuit controller y^3 , and contact $25-25^a$ of circuit controller y^3 to terminal o .

With signals S^1 indicating stop, approach locking relay P^{S1} is energized by its circuit passing from terminal x , through contacts 29 , 30 and 31 of signals S^{1c} , S^{1b} and S^{1a} , respectively, contact 32 of relay T^1 in multiple with contact 35 of relay P^{S1} , and the winding of relay P^{S1} to terminal o . Approach locking relay P^{S4} is energized by a circuit which is similar to that just traced for relay P^{S1} .

With signal S^2 indicating stop, stick locking relay Q^{S2} is energized by its stick circuit passing from terminal x , through contact 36 of signal S^2 , contact 38 of relay Q^{S2} , and the winding of relay Q^{S2} to terminal o . Stick locking relays Q^{S3} , Q^{S5} and Q^{S6} are energized by circuits which are similar to the circuit just traced for relay Q^{S2} .

With all approach and stick locking relays P and Q , respectively energized, and with all track relays T energized, all of the route locking relays V^e and V^w are energized as shown in Fig. 8. For example, relay V^{2ae} is energized by its pick-up circuit passing from terminal x , through contacts 43^{Qs1} , 44^{Qs2} , contact 45^{PS1} in multiple with contact 46^{h2} , contact 47^{T2} in multiple with contact 48^{h2} , contacts 49^{T5} and 50^{T6} , and the winding of relay V^{2ae} to terminal o . A stick circuit is also closed for relay V^{2ae} , which includes the pick-up circuit just traced as far as contacts 45^{PS1} and 46^{h2} , and thence passes through contact 51 of relay V^{2ae} , and the winding of relay V^{2ae} to terminal o .

Each of the signal stick relays L^{S1} and L^{S4} , shown in Fig. 9, is energized, both a pick-up and a stick circuit for each of these relays being closed. The circuits for relay L^{S1} are closed because certain track relays are energized, and

because switches H^2 and H^{2a} are in their normal position. The pick-up circuit for relay L^{S1} passes from terminal x , through contacts 74^{h2} , 75^{T2} , 76^{T4} , 79^{T2} , 80^{PS1} , and the winding of relay L^{S1} to terminal o . The stick circuit which is closed for relay L^{S1} is the same as the pick-up circuit just traced except including contact 81 of relay L^{S1} instead of contact 80^{PS1} . The pick-up circuit just traced except including contact 81 of relay L^{S1} instead of contact 80^{PS1} . The pick-up and stick circuits for relay L^{S4} are similar, respectively, to those just traced for relay L^{S1} , and will therefore be readily understood by reference to the drawings.

15 I will assume that the operator desires to arrange for a traffic movement over route 1 from A to E. He, therefore, rotates device K^1 to its position r^{1E} and then deflects device K^1 , thereby closing contact 51^E . Meanwhile, arm 7 of contact 7^{K1} connects with segment 7^a , completing a pick-up circuit for relay W^1 , passing from terminal x , through contacts 99^{2E} , 99^{2F} , 91^{23E} , 92^{63F} , 93^{64A} , wire 94 , contacts 95^{W5} , 96^{W6} and 7^{K1} , and the winding of relay W^1 to terminal o . Relay W^1 , upon becoming energized, as just described, continues energized by a stick circuit which is the same as the pick-up circuit just traced as far as contact 96^{W6} , and thence passing through contacts 9^{K1n} , 97^{T2} , and 99 of relay W^1 , and the winding of relay W^1 to terminal o . Relay W^1 , upon becoming energized, completes, through its contact 131^{W1} , a circuit for indicator lamp e^1 , shown in Fig. 7, causing this lamp to become lighted. As long as lamp e^1 continues lighted, the operator therefore knows that master route relay W^1 is energized. Upon the closing of the front contacts of relay W^1 and the closing of contact 51^E , relay g^{1E} becomes energized by its pick-up circuit passing from terminal x , through contacts 174^{W1} and 51^E , and the winding of relay g^{1E} to terminal o . Relay g^{1E} , upon becoming energized, continues energized by its stick circuit passing from terminal x , through contact 174^{W1} , contact 175 of relay g^{1E} , and the winding of relay g^{1E} to terminal o .

Relay g^{1E} , upon becoming energized, completes a circuit for relay X^2 , shown in Fig. 10, passing from terminal x , through contacts 282^{R2} and $203g^{1E}$, and the winding of relay X^2 to terminal o . Relay g^{1E} , upon becoming energized, also completes a circuit for relay X^3 passing from terminal x , through contacts 222^{R3} and $224g^{1E}$, and the winding of relay X^3 to terminal o . Relay g^{1E} also completes a circuit for relay X^4 passing from terminal x , through contacts 244^{R4} and $245g^{1E}$, and the winding of relay X^4 to terminal o . With relay X^2 energized, relay m^2 , shown in Fig. 11, becomes energized in the normal direction by a circuit passing from battery k^2 , through contacts 264^{R2} , 266^{X2} , $267V^{3w}$, $269V^{2aw}$, $270V^{2ae}$, 271^{PS1} , 272^{T2} and 273^{T6} , and the winding of relay m^2 back to battery k^2 . With relay X^3 energized, relay m^3 is similarly energized in the normal direction by a circuit passing through contact 276^{X3} . With relay X^4 energized, relay m^4 is likewise energized in the normal direction by a circuit passing through contact 285^{X4} .

70 Relay Y^1 , shown in Fig. 12, becomes energized, after the energization of relays X^2 , X^3 and X^4 by a circuit passing from terminal x , through contacts 383^{W5} , 384^{W4} , 387^{h4} , 388^{h4} , 389^{h3} , 390^{h3} , 391^{X3} , 392^{X2} , 393^{h2} , 394^{h2} and 395^{W1} , and the winding of relay Y^1 to terminal o . Upon the energization of relay Y^1 , the arm of signal S^{1a} becomes operated to its proceed position by a circuit passing from

terminal x , through contacts $324g^{1E}$, 328^{QS5} , 329^{W5} , 336^{h4} , 337^{h4} , 338^{h3} , 339^{h3} , 340^{h2} , 341^{h2} , front point of contact 342^{W1} , contact 343^{JS1} , back point of contact 344^{ZS1} , contacts 345^{LS1} and 346^{Y1} , back point of contact 347^{e1F} , contact $348g^{1E}$, contact 349 of signal S^{1b} , and the mechanism of signal S^{1a} to terminal o . 5

When the arm of signal S^{1a} leaves its stop position, both the pick-up and stick circuits previously traced for relay P^{S1} are opened at contact 31 of signal S^{1a} . With relay P^{S1} deenergized, the pick-up circuit for relay L^{S1} , shown in Fig. 9, is open at contact 80^{PS1} but the stick circuit for relay L^{S1} continues closed and hence relay L^{S1} continues energized. 15

Upon the deenergization of relay P^{S1} , contact 45^{PS1} opens in the circuit for relay V^{2ae} , shown in Fig. 8, but relay V^{2ae} continues energized by a branch path through contact 46^{h2} . Relay P^{S1} , upon becoming deenergized, opens, at its contact 55^{PS1} , the pick-up and stick circuits for relay V^{3e} , causing relay V^{3e} to become deenergized. With relay V^{3e} deenergized, the circuits for relays m^3 and m^4 are open at contacts 273^{V3e} and 286^{V3e} , respectively, thus making it impossible to supply current to these circuits which might cause relays m^3 and m^4 to become energized in the reverse direction. The circuit for relay m^2 is also now open at contact 271^{PS1} on account of relay P^{S1} being deenergized. 30

An eastbound train approaching signal S^{1a} after the route from A to E has been arranged as just described, deenergizes approach track relay T^1 which then opens its contact 32 in the circuit for relay P^{S1} which, however, is already open at contact 31 of signal S^{1a} . 35

When the train passes signal S^{1a} , entering section A—ii, relay T^2 becomes deenergized, thereupon opening its contact 97^{T2} in the stick circuit previously traced for relay W^1 and so causing relay W^1 to become deenergized. Relay W^1 , upon becoming deenergized, opens its contact 174^{W1} , causing relay g^{1E} to become deenergized. Relay W^1 , upon becoming deenergized, also opens its contact 342^{W1} in the circuit for signal S^{1a} , causing the arm of signal S^{1a} to return to the stop position. Relay W^1 , upon becoming deenergized, also opens its contact 131^{W1} , causing lamp e^1 to be extinguished and to thus indicate to the operator that relay W^1 is deenergized. With relay g^{1E} deenergized, relays X^2 , X^3 and X^4 are deenergized on account of the opening of contacts 283^{S1E} , $224g^{1E}$ and $245g^{1E}$, respectively. 50

The arm of signal S^{1a} , upon again reaching its stop position, completes a pick-up circuit for relay P^{S1} passing from terminal x , through contacts 29 , 30 and 31 of signals S^{1c} , S^{1b} and S^{1a} , respectively, contact 33 of relay T^2 , and the winding of relay P^{S1} to terminal o . 55

Relay T^2 , upon becoming deenergized, also opens its contact 79^{T2} , causing relay L^{S1} to become deenergized. 60

When the train moves out of section A—ii, relay T^1 becomes energized, completing again the pick-up circuit first traced for relay P^{S1} through contact 32 of relay T^1 . 65

When the train moves out of section A—ii, relay T^2 again becomes energized. While the train is in section ii—jj, relay T^3 is deenergized, causing relays L^{S1} and V^{3e} to continue deenergized. When the train leaves section ii—jj, permitting relay T^3 to again become energized, relay V^{3e} becomes energized by its pick-up circuit passing from terminal x , through contacts 55^{PS1} . 70

57^{V3ae}, 57^{T2}, and 61^{T3}, and the winding of relay V^{3e} to terminal o.

5 While the train is in section *jj*—E, causing relay T^4 to be deenergized, contact $16T^4$ is open, causing relay L^{S1} to continue deenergized. When the train leaves section *jj*—E, relay T^4 , upon becoming energized, causes relay L^{S1} to again become energized by its pick-up circuit previously traced, and thus completes restoration, to the 10 normal condition, of all parts of the apparatus for the control of the route from A to E.

If, after a route has been arranged for a traffic

movement as, for example, the route from A to E as previously described, a train has entered the route and it is then desired to provide a call-on signal indication to authorize a second train to enter the route while it is still occupied by the first train, the operator will rotate device K^1 to its r^{1S} position and will there deflect device K^1 to close contact 5^{1S} , thereby completing a pick-up circuit for relay Z^{S1} , shown in Fig. 6, passing from terminal x , through contact 5^{1S} , and the winding of relay Z^{S1} to terminal o . The rotation of device K^1 , toward the right, causes relay W^1 to again become energized by its pick-up circuit previously traced. With relay Z^{S1} energized, relay W^1 will continue energized, after device K^1 has been returned to its n position, by a stick circuit which is the same as the stick circuit previously traced for relay W^1 , except passing through contact 98^{ZS1} instead of contact 97^{T2} . With relay W^1 energized, relay Z^{S1} will continue energized by its stick circuit passing from terminal x , through contact 364^{W1} , contact 365 of relay Z^{S1} , and the winding of relay Z^{S1} to terminal o . The operator will then rotate device K^1 to its r^{1E} position, causing relay g^{1E} to again become energized.

40 Relay g^{1E} , upon becoming energized, causes relays X^2 , X^3 and X^4 to again become energized by the circuits previously traced. With relays X^2 , X^3 , X^4 and W^1 again energized, relay Y^1 becomes energized by its circuit previously traced.

45 With relay Y^1 energized while relay Z^{S1} is energized, a circuit is now completed for signal S^{1c} , which is the same as the circuit previously traced for signal S^{1a} as far as contact $343J^{S1}$, thence passing through the front point of contact 344^{ZS1} , contact 352^{Y^1} , contacts 353 and 354 of signals S^{1a} and S^{1b} , respectively, and the mechanism of signal S^{1c} to terminal o . The arm of signal S^{1c} thereupon moves to its call-on position. Since the circuit just traced for signal S^{1c} does not include a contact of stick relay L^{S1} , the arm of signal S^{1c} will continue to indicate "call-on" after a second train has entered the route.

To return the arm of signal S^{1c} to its stop position, the operator will deflect device K^1 in its n position, thereby breaking the stick circuit for relay W^1 at contact 6^{K1n} . Relay W^1 being deenergized, relays Z^{S1} and g^{IE} are deenergized by the opening of contacts 364^{W1} and 174^{W1} , respectively, and all parts of the apparatus for controlling the route are thus returned to their normal condition.

I will now assume that with all parts of the apparatus again in their normal condition as previously described, the operator arranges route 70 1 for a traffic movement from A to E and clears signal S^{1A}, as also previously described, by deflecting device K¹ in its r^{1E} position and so closing contact 5^{1E}. If, now, after an eastbound 75 train enters section a—A, deenergizing relay T¹,

the operator should desire to send this train over some other route than route 1, he will deflect device K^1 in its n position, thereby deenergizing relay W^1 by opening contact 6^{K^1n} . Relay W^1 , upon becoming deenergized, causes relay g^{1E} to again become deenergized. With relay W^1 deenergized, the circuit previously traced for signals S^{1a} is open at contact 342^{W1} , causing the arm of signal S^{1a} to move to the stop position. 5

On account of relay T^1 being deenergized by the train in section a —A, relay P^{S^1} does not pick up when the arm of signal S^{1a} is returned to its stop position. In order to energize relay P^{S^1} , the operator will start the operation of clockwork time release J^{S^1} . Contact $34J^{S^1}$ in the circuits for signals S^1 , shown in Fig. 13, will immediately open, and after the lapse of a measured interval of time, contact 34 of release J^{S^1} will close, causing relay P^{S^1} to become energized by a third pick-up circuit passing from terminal x , through contacts 29 , 30 and 31 of signals S^{1c} , S^{1b} and S^{1a} , respectively, contact 34 of release J^{S^1} , and the winding of relay P^{S^1} to terminal o . With relay P^{S^1} energized, relay V^{3e} will become energized by its pick-up circuit previously traced, and hence the operator can now proceed to arrange any other route originating at point A, but signal S^{1b} or S^{1c} can not be operated to the proceed position for governing over such a route until the operator restores the contacts of release J^{S^1} to their normal position.

Assuming that the operator wishes to send the train, which has arrived in section a — A , over route 2 from A to F , he will deflect device K^1 in its r^{1F} position, thereby closing contact 5^{1F} and completing a pick-up circuit for relay g^{1F} since relay W^1 is now energized by its pick-up circuit previously traced. The circuit for relay g^{1F} passes from terminal x , through contacts 176^{s1E} , 177^{W1} and 5^{1F} , and the winding of relay g^{1F} to terminal o . With relay g^{1F} energized, relay X^2 becomes energized by a circuit passing from terminal x , through contact 204^{g1F} , and the winding of relay X^2 to terminal o . Relay X^3 also becomes energized by a circuit passing from terminal x , through contacts 222^{R3} and 225^{s1F} , and the winding of relay X^3 to terminal o . Relay R^4 becomes energized by a circuit passing from terminal x , through contacts 250^{X4} and 251^{g1F} , and the winding of relay R^4 to terminal o .

With relays X^2 and X^3 energized, relays m^2 and m^3 again become energized in the normal direction as previously described. With relay R^4 energized, relay m^4 becomes energized in the reverse direction by a circuit passing from battery k^3 , through the winding of relay m^4 , contacts 289^{T4} , 288^{QS6} , 287^{QS5} , 286^{V3e} , back point of contact 825^{X4} , and contact 284^{R4} back to battery k^3 . With relay m^4 energized in the reverse direction, motor M^4 is supplied with current for moving switch H^4 to its reverse position, such current passing from battery k^1 , through contact 11^{m4} closed in the reverse position, armature 12 of motor M^4 , asymmetric unit i^2 , field winding 13 of motor M^4 , contact 16 of circuit controller y^4 , asymmetric unit i^4 , and contact 15^{m4} closed in the reverse position, back to battery k^1 . Upon the reversal of the polar contacts of relay m^4 , terminal x is disconnected from indication relay h^4 , and a shunt circuit is completed for relay h^4 passing from contact 20^{m4} closed in the reverse position, through contact 18^a-18 of circuit controller y^4 , the winding of relay h^4 , the contact $19-19^a$ of circuit controller y^4 back to contact 20^{m4} . During the movement 75

- of switch H^4 from its normal to its reverse position, indication relay h^4 is shunted by a second circuit including contacts $18-13^c$ and 19^c-19 of circuit controller y^4 . Upon the completion of the 6 operation of switch H^4 to its reverse position, relay h^4 becomes energized in the reverse direction by a circuit passing from terminal x , through contact 17^{h4} closed in the reverse position, contact 19^b-19 of circuit controller y^4 , winding of 10 relay h^4 , and contact $18-13^b$ of circuit controller y^4 , to terminal o .
- Upon the energization of relay h^4 in the reverse direction, relay Y^1 becomes energized by a circuit passing from terminal x , through back point of 15 contact 385^{W6} , contact 396^{R4} , contact 387^{h4} closed in its reverse position, contacts 388^{h4} , 389^{h3} , 390^{h3} , 384^{X3} , 392^{X2} , 393^{h2} , 394^{h2} , front point of contact 395^{W1} , and the winding of relay Y^1 to terminal o . Upon the energization of relay Y^1 , the arm of signal S^{1b} becomes operated to its proceed position by a circuit passing from terminal x , through contacts 390^{G1F} and 334^{QS6} , back point of contact 335^{W6} , contact 336^{h4} closed in the reverse position, contact 337^{h4} , 388^{h3} , 339^{h3} , 340^{h2} , 341^{h2} , 20 front point of contact 342^{W1} , contact 343^{JS1} , back point of contact 344^{ZS1} , contact 345^{LS1} , contact 346^{Y1} , front point of contact 347^{G1F} , contact 350 of signal S^{1a} , and the mechanism of S^{1b} to terminal o .
- 25 When the arm of signal S^{1b} leaves its stop position approach locking relay P^{S1} becomes deenergized by the opening of contact 39 of signal S^{1b} , shown in Fig. 1. If, now, a train moves over the route from A to F, the control apparatus will 30 be restored to its normal condition similarly to the manner described in connection with a traffic movement through the route from A to E. Switch H^4 will, however, remain in its reverse position until the operator causes it to be re- 35 turned to the normal position by the operation of a device K for the control of some route which includes switch H^4 in its normal position.
- Assuming, now, that all parts of the apparatus 40 are again in their normal condition, as previously described, and that the operator desires to arrange for a traffic movement over route 3 from A to D, he will rotate device K¹ to its r^{1D} position where he will deflect device K¹ to close contact 5^{1D} and thereby complete a pick-up circuit for 45 relay g^{1D} passing from terminal x through contacts 137^{W2} , 138^{W3} , 139^{W4} , 140^{W1} , 5^{1D} , and the winding of relay g^{1D} to terminal o . Relay g^{1D} , after becoming energized, continues energized by its stick circuit through its contact 141 as long as 50 relay W^1 continues energized.
- 55 Relay g^{1D} , upon becoming energized, causes relay R^2 to become energized by a circuit passing from terminal x , through contacts 215^{X2} and 216^{G1D} , and the winding of relay R^2 to terminal o .
- 60 Relay g^{1D} also causes relay X^3 to be energized by a circuit passing from terminal x , through contacts 222^{R2} and 223^{G1D} , and the winding of relay X^3 to terminal o . The energization of relay R^2 causes relay m^2 to be energized in the reverse direction by a circuit passing through contact 265^{R2} and similar to the reverse control circuit previously described for relay m^4 . Relay X^3 , upon becoming energized, causes relay m^3 to be energized in the normal direction as previously 65 described. Upon the reversal of the polar contacts of relay m^2 , relay h^2 , the normal control circuit for which is similar to that shown for relay h^3 , will become deenergized, and will be provided with a shunt path through a reverse polar contact of relay m^2 . Another shunt path will be

completed for relay h^2 during the operation of switches H^2 and H^{2a} from the normal to the reverse position. Upon the completion of the operation of switches H^2 and H^{2a} to the reverse position, relay h^2 will become energized in the reverse direction by a reverse control circuit which is similar to that shown for relay h^3 . 5

With relay h^2 energized in the reverse direction, relay Y^1 will become energized by a circuit passing from terminal x , through contacts 389^{W4} , 379^{X3} , contact 378^{h3} closed in the normal position, contacts 377^{h3} , 376^{h2} , 375^{h2} closed in the reverse position, contact 381^{R2} , front point of contact 395^{W1} , and the winding of relay Y^1 to terminal o . Upon the energization of relay Y^1 , the arm of signal S^{1c} will be operated to the proceed position by a circuit passing from terminal x , through contacts 318^{G1D} , 321^{PS4} , 306^{W4} , contact 305^{h3} closed in the normal position, contacts 304^{h3} , 303^{h2} , contact 302^{h2} closed in the reverse position, front point of contact 351^{W1} , contact 352^{Y1} , contacts 353 and 354 of signals S^{1a} and S^{1b} , respectively, and the mechanism of signal S^{1c} to terminal o . 15

I will next assume that all parts of the apparatus are again in the normal condition and that the operator wishes to send a train by route 4 from A to E. He will therefore move device K¹ to its r^{1GE} position, and will there deflect device K¹ to close contact 5^{1GE} . By closing contact 5^{1GE} , the operator completes a pick-up circuit for 20 relay g^{1GE} passing from terminal x , through contacts 137^{W2} , 138^{W3} , 139^{W4} , 142^{W1} , 5^{1GE} , and the winding of relay g^{1GE} to terminal o . Upon the energization of relay g^{1GE} , this relay continues energized by a stick circuit which is the same as 25 the pick-up circuit just traced except including contact 143 of relay g^{1GE} instead of contact 5^{1GE} .

With relay g^{1GE} energized, relay R^2 is energized by a circuit through contact 217^{G1GE} , relay R^3 is 30 energized by a circuit through contact 232^{G1GE} , and relay X^4 is energized by a circuit through contact 246^{G1GE} . With relays R^2 and R^3 energized, polarized relays m^2 and m^3 are energized in their reverse direction, and with relay X^4 energized, relay m^4 is energized in the normal direction. Switches H^2 , H^{2a} , H^{3a} and H^3 will accordingly be operated to their reverse positions, and switch H^4 will remain in its normal position.

Upon the completion of the arrangement of 50 switches H^2 , H^{2a} , H^{3a} , H^3 and H^4 in these positions, respectively, relay Y^1 will become energized by a circuit passing from terminal x , through contacts 383^{W5} , 384^{X4} , contact 387^{h4} closed in the normal position, contacts 388^{h4} , 382^{R3} , contact 378^{h3} 55 closed in the reverse position, contacts 377^{h3} , 376^{h2} , contact 375^{h2} closed in the reverse position, contact 381^{R2} , front point of contact 395^{W1} , and the winding of relay Y^1 to terminal o . With relay Y^1 energized, the arm of signal S^{1c} will be operated to the proceed position by a circuit passing from terminal x , through contacts 325^{G1GE} , 328^{QS5} , back point of contact 329^{W5} , contact 336^{h4} closed in the normal position, contact 337^{h4} , contact 395^{h3} closed in the reverse position, contacts 304^{h3} , 303^{h2} , contact 302^{h2} closed in the reverse position, front point of contact 351^{W1} , contact 352^{Y1} , contact 353 of signal S^{1a} , contact 354 of signal S^{1b} , and the mechanism of signal S^{1c} to terminal o . 60

Relay $PS1$ becomes deenergized by the opening of contact 29 when the arm of signal S^{1c} leaves the stop position. With relay h^2 energized in the reverse direction, contact 46^{h2} , shown in the circuit for relay V^{2ae} in Fig. 8, is open and hence relay V^{2ae} becomes deenergized upon the deener- 75

gization of relay P^{S1} which causes contact 45^{PS1} in the circuit for relay V^{2ae} to open. The deenergization of relay V^{2ae} causes contact $52^{V^{2ae}}$ to be opened in the circuit for relay V^{3ae} , and thus relay V^{3ae} becomes deenergized. On account of relay h^3 being energized in the reverse direction, contact 58^{h^3} in the circuit for relay V^{3e} is open, and hence relay V^{3e} becomes deenergized when relay V^{3ae} opens contact $57^{V^{3ae}}$ in the circuit for relay V^{3e} . With relay V^{2ae} deenergized, the circuits for relay m^2 are open at contact $278^{V^{2ae}}$. With relay V^{3e} deenergized, the circuits for relays m^3 and m^4 are open at contacts $278^{V^{3e}}$ and $286^{V^{3e}}$, respectively.

To arrange for a traffic movement over route 6, from B to D, when all parts of the apparatus have been again returned to their normal condition, the operator will rotate device K^2 to its r^{2D} position. Just after the beginning of this movement of device K^2 , contact 7^{K^2} , operated by device K^2 , becomes closed, completing a pick-up circuit for relay W^2 passing from terminal x , through contacts 198^{g1D} , 199^{g1GE} , 199^{g1GF} , 111^{g5C} , 112^{g5B} , 113^{g5GA} , 114^{g6C} , 115^{g6B} , 116^{g6GA} , wire 122 , contacts 123^{W^4} , 124^{W^3} and 7^{K^2} , and the winding of relay W^2 to terminal o . The operator will then deflect device K^2 at its position r^{2D} to close contact 5^{2D} , thus completing a pick-up circuit for relay g^{2D} passing from terminal x , through contacts 179^{W^2} and 5^{2D} , and the winding of relay g^{2D} to terminal o . With relay W^2 energized, relays X^1 and X^2 become energized by circuits through contacts 193^{W^2} and 225^{W^2} , respectively. With relay g^{2D} energized, relay X^3 becomes energized by a circuit through contact 226^{g2D} . Upon the energization of relays X^1 , X^2 and X^3 , relays m^1 , m^2 and m^3 , respectively, will become energized in the normal direction causing switches H^1 , H^2 and H^3 to be operated to their normal position if they were not already in such position.

Upon the completion of the arrangement of these switches in their normal positions, relays h^1 , h^2 and h^3 become energized in the normal direction, completing a circuit for relay Y^2 passing from terminal x , through contacts 389^{W^4} , 379^{X^3} , contact 378^{h^3} closed in the normal position, contacts 377^{h^3} , 376^{h^2} , contact 375^{h^2} closed in the normal position, contacts 374^{X^2} , 373^{h^1} , contact 372^{h^1} closed in the normal position, contact 369^{X^1} , front point of contact 368^{W^2} , and the winding of relay Y^2 to terminal o . With relay Y^2 energized, the arm of signal S^2 is operated to the proceed position by a circuit passing from terminal x , through contacts 319^{g2D} , 321^{PS4} , back point of contact 306^{W^4} , contact 305^{h^3} closed in the normal direction, contacts 304^{h^3} , 303^{h^2} , contact 302^{h^2} closed in the normal position, contact 301^{h^1} , contact 300^{h^1} closed in the normal position, front point of contact 294^{W^2} , contact 323^{Y^2} , and the mechanism of signal S^2 to terminal o . When the arm of signal S^2 leaves its stop position stick locking relay Q^{S2} becomes deenergized by the opening of contact 36 to signal S^2 .

If a train passes signal S^2 into section B— mm , relay T^5 becomes deenergized, opening the stick circuit for relay W^2 at contact 125^{T^5} . Relay W^2 , becoming thereby deenergized, opens, at its contact 179^{W^2} , the stick circuit for relay g^{2D} . With relays W^2 and g^{2D} deenergized, relays X^1 , X^2 and X^3 become deenergized, causing relay Y^2 to also become deenergized. Upon the deenergization of relay W^2 , the arm of signal S^2 will return to its stop position. As soon as the arm of signal S^2 returns to its stop position, relay Q^{S2} will become energized by its pick-up circuit passing

from terminal x , through contact 36 of signal S^2 , contact 37^{T^5} , and the winding of relay Q^{S2} to terminal o .

If, on the other hand, before a train passes signal S^2 , the operator desires to arrange some other route, he will return the arm of signal S^2 to its stop position by deflecting device K^2 at its n position to open contact 6^{K2n} , thereby breaking the stick circuit for relay W^2 . Relay W^2 , upon becoming deenergized, opens at its contact 368^{W^2} the circuit for relay Y^2 , causing this relay to become deenergized. Relay W^2 , upon becoming deenergized, also opens at its contact 294^{W^2} the circuit for signal S^2 , the arm of which then returns to its stop position. With the arm of signal S^2 in its stop position, winding 40 of thermal relay N^{S2} , which is associated with relay Q^{S2} shown in Fig. 1, becomes energized by its circuit passing from terminal x , through contact 36 of signal S^2 , winding 40 , and contact 41 of relay Q^{S2} to terminal o . Upon the lapse of a sufficient period of time, relay N^{S2} then closes its contact 39 , completing a second pick-up circuit for relay Q^{S2} , passing from terminal x , through contact 36 of signal S^2 , contact 39 of relay N^{S2} , and the winding of relay Q^{S2} to terminal o . When relay Q^{S2} becomes energized, the operator can arrange any other route he desires.

I will now describe the second form of apparatus embodying my invention, comprising parts shown in Figs. 1, 2, 6, 7, 8, 9, 11, 14, 15, 16 and 17. In considering the first form of apparatus embodying my invention, I have already discussed the parts shown in Figs. 1, 2, 6, 7, 8, 9 and 11.

Parts shown in Fig. 14 are similar to the parts shown in Figs. 3 and 3a, except that each of the devices K , shown in Fig. 14, operates a plurality of exit contacts 5 when deflected at certain positions r , whereas in Figs. 3 and 3a, only one contact 5 is operated in each position r .

In Fig. 15, no inter-control is shown for relays W through back contacts of auxiliary route relays g or through back contacts of other relays W . Otherwise the circuits for each relay W are exactly as in Fig. 5.

In Fig. 16, each normal switch control relay X and each reverse switch control relay R is controlled through a back contact of the reverse or normal switch control relay R or X , respectively, for the same route, as is also shown in Fig. 10. Pick-up circuits for certain of the X and R relays are also controlled through contacts of certain relays W as in Fig. 10. In the pick-up circuits shown in Fig. 16, contacts 5 are used instead of the contacts, shown in Fig. 10, of auxiliary route relays g which are controlled by similar contacts 5 . In addition to the pick-up circuits, stick circuits are shown for each relay X and R in Fig. 16. These stick circuits are controlled by the relays W for the routes for which contacts 5 are shown in the pick-up circuits for the same relays.

Fig. 17 shows the signal control circuits for the second form of apparatus embodying my invention.

As shown in the drawings, all parts of the second form of apparatus embodying my invention are in the normal condition. I will now assume that with all parts thus in the normal condition, the operator desired to arrange for a traffic movement over route 1 from A to E. He therefore moves device K^1 to its r^{1E} position, and there deflects device K to close exit contacts 5^{1E2} , 5^{1E3} and 5^{1E4} , shown in Fig. 14. During this movement of device K^1 , entrance contact 7^{K^1} oper-

ated by device K^1 becomes closed, causing relay W^1 to become energized by its pick-up circuit shown in Fig. 15. Relay W^1 then continues energized by its stick circuit passing from terminal x , through contacts 6^{K1n} , 97^{T2} , 69 of relay W^1 , and winding of relay W^1 to terminal o .

Upon the closing of contact 5^{E2} , relay X^2 becomes energized by its pick-up circuit passing from terminal x , through contacts 202^{R2} , 5^{E2} , and the winding of relay X^2 to terminal o . On account of relay W^1 being energized, relay X^2 then continues energized by its stick circuit passing from terminal x , through contacts 222^{R2} , 404^{W1} , 419 of relay X^2 , and the winding of relay X^2 to terminal o . When contact 5^{E3} becomes closed, relay X^3 becomes energized by a pick-up circuit passing from terminal x , through contacts 222^{R3} and 5^{E3} , and the winding of relay X^3 to terminal o . Relay X^3 then continues energized by a stick circuit passing from terminal x , through contacts 222^{R3} , 414^{W1} , 419 of relay X^3 , and the winding of relay X^3 to terminal o . Upon the closing of contacts 5^{E4} , relay X^4 becomes energized by a pick-up circuit which is similar to the pick-up circuits just traced for relays X^2 and X^3 . Relay X^4 then continues energized by a stick circuit which is similar to the stick circuits just traced for relays X^2 and X^3 . With relays X^2 , X^3 and X^4 energized, relays m^2 , m^3 and m^4 become energized in the normal direction, causing corresponding switches to be operated to their normal positions if they were not already in such positions.

Upon the completion of the arrangement of these switches in their normal positions and the subsequent energization of relays h^2 , h^3 and h^4 in the normal direction, the arm of the signal S^{1a} becomes operated to its proceed position by a circuit shown in Fig. 17, passing from terminal x , through contact 328^{QS5} , back point of contact 229^{W5} , contact 445^{X4} , contact 336^{h4} closed in the normal position, contacts 337^{h4} , 338^{h3} , 339^{h3} , 340^{h2} , 341^{h2} , 447^{X3} , 448^{X2} , front point of contact 342^{W1} , contact 343^{JS1} , back point of contact 344^{ZS1} , contact 345^{LS1} , back point of contact 449^{R4} , contact 451^{X4} , contact 349 of signal S^{1b} , and the mechanism of signal S^{1a} to terminal o .

When the arm of signal S^{1a} leaves the stop position, its contact 31 opens, thereby deenergizing relay P^{S1} . An eastbound train approaching signal S^{1a} , after the route from A to E has been arranged as just described, deenergizes approach track relay T^1 , which then opens its contact 32 in the pick-up circuit for relay P^{S1} which, however, is already open at contact 31 of signal S^{1a} .

When the train passes signal S^{1a} , entering section A-ii, relay T^2 becomes deenergized, closing its contact 33 . The deenergization of relay T^2 causes relay W^1 to become deenergized on account of the opening of contact 97^{T2} in the stick circuit for relay W^1 . Relay W^1 , upon becoming deenergized, breaks, at its contacts 404^{W1} , 414^{W1} and 426^{W1} , the stick circuits for relays X^2 , X^3 and X^4 , respectively, causing these relays to become deenergized. Relay W^1 , upon becoming deenergized, also opens its contact 342^{W1} in the circuit for signal S^{1a} , causing the arm of signal S^{1a} to return to the stop position. With the arm of the signal again in the stop position, relay P^{S1} becomes energized by its pick-up circuit previously traced through contact 31 of signal S^{1a} and contact 33 of relay T^2 .

I will assume that with all parts of the appa-

ratus again in the normal condition, as previously described, the operator arranges route 1 for a movement from A to E, and clears signal S^{1a} , as already described, by deflecting device K^1 in its r^{1E} position. If, now, after an eastbound train enters section a-A, deenergizing relay T^1 , the operator should desire to send the train over some other route than route 1, he will deflect device K^1 in its n position, thus deenergizing relay W^1 by opening contact 6^{K1n} . The deenergization of relay W^1 causes relays X^2 , X^3 and X^4 to become deenergized, and causes the arm of signal S^{1a} to be returned to the stop position as already described. Relay P^{S1} can then be again energized by the operation of time releasing device J^{S1} as already set forth in connection with the first form of apparatus embodying my invention.

I have described, for a few typical traffic movements, the operation of two forms of apparatus embodying my invention. From those descriptions and from the preceding general description, the operation of each of the two forms of the apparatus for every other possible traffic movement will be readily understood by reference to the drawings.

Apparatus of each of the two forms embodying my invention is shown for a layout providing switches which can be arranged for eleven different routes. Traffic movements can be made in either direction over each of these routes. The arranging of the switches in these eleven routes, and the clearing of signals for eastbound traffic movements through these routes, are controlled by three rotatable devices, here shown as K^1 , K^2 and K^3 , which may be mounted on a track model and operating board as shown in Fig. 2. For westbound traffic movements, the switches and signals for these eleven routes are controlled by three other rotatable devices, designated by the reference characters K^4 , K^5 and K^6 , respectively, and also shown in Fig. 2. It follows that only six of these rotatable push button devices are required for the complete control of the switches and signals for the eleven routes, in both directions of traffic movement, including call-on signal control. Only one manual operation is required for arranging any route and clearing the signal for the route, such operation comprising the rotation of a push button corresponding to the entrance end of the route to a position corresponding to the exit end of the route, and the deflection of the push button in that position. The rotatable push button devices, as here shown, are arranged for automatic restoration to the normal position, but could instead be arranged for manual restoration to the normal position if desired.

From the examples of operation cited, it is clear that in order to arrange any route and clear the signal for a given direction of traffic over such route, the operator has, under normal conditions, only to move a device K associated with the entrance end of the route to one of its positions r to close a contact 7 and to then deflect the device K to close a contact or contacts 5 corresponding to the exit end of the desired route. The device K will, in the form here shown, then be returned to its n position by its spring 8 , or the device K , if it is not equipped with a spring 8 , can be manually returned to its n position. When a train enters the route, the master relay W for the route will become deenergized if the device K for the route is returned to its n position before the train

leaves the first track section in the route. If, however, the operator wishes to return a signal to the stop position or to prepare to change the route before a train enters the route, he can do so by deflecting the same device K in its n position and thereby opening the corresponding contact, such, for example as contact 6^{K1n} of device K^1 . He can then arrange another route by deflecting a corresponding device in a corresponding r position.

Complete route interlocking is provided by each of the two forms of apparatus embodying my invention. In each of the two forms, the interlocking of routes controlled by the same device K is accomplished by the inter-control of the normal and reverse switch control relays X and R . In the first form of apparatus embodying my invention, the interlocking of all other routes is accomplished by the inter-control of the master and auxiliary route control relays W and g , respectively. In the second form of apparatus embodying my invention, the interlocking of other routes than those controlled by the same device K is accomplished by the control of stick circuits, in addition to certain pick-up circuits of the X and R relays, by master route relays W .

The apparatus shown in Fig. 12 for the first form of apparatus embodying my invention could, if desired, be omitted, as this is merely a duplication of the control accorded by other parts of the apparatus shown for the first form.

From the circuits of Figs. 13 and 17, it is clear that in either form of apparatus embodying my invention, no signal can be clear until each switch within the route governed by the signal is in the correct position. It is also clear that conflicting signal indications can not be displayed.

Concentration of the control apparatus of my invention makes it possible to control a given layout of switches and signals by a minimum total number of control units and control relays. Apparatus embodying my invention is therefore particularly adapted to the control of complicated yard layouts as well as the more simple layouts.

With apparatus embodying my invention, complicated circuits are avoided, the individual circuits employed being comparatively simple in design. The circuits, as here shown, are designed for causing the master route control relays to be automatically restored to the deenergized condition upon the entrance of a train into a corresponding route. Provision is also made for manual restoration of the master route control relays to the deenergized condition.

As has been described, my invention provides approach or strict locking, and detector track circuit locking, as well as route locking and signal indication locking, for all switches.

Although I have herein shown and described only two forms of multiple control apparatus embodying my invention, it is understood that various changes and modifications may be made therein within the scope of the appended claims without departing from the spirit and scope of my invention.

Having thus described my invention, what I claim is:

1. Railway control apparatus comprising a diagram of a stretch of railway track which includes a plurality of routes comprising a plurality of railway traffic governing devices, and a circuit controller mounted adjacent said diagram and having a plurality of rotatory circuit closing positions for selectively arranging said

traffic governing devices in said plurality of routes.

2. Railway control apparatus comprising a diagram of a stretch of railway track which includes a plurality of partly inter-inclusive routes comprising a plurality of railway traffic governing devices, a circuit controller mounted adjacent said diagram at the representation of each point of traffic entrance for said stretch respectively, and each of said circuit controllers having a plurality of rotatory circuit closing positions for selectively arranging a plurality of traffic governing devices in a plurality of routes which begin at the corresponding point of traffic entrance to said stretch.

3. Railway control apparatus comprising a diagram of a stretch of railway track which includes a plurality of partly inter-inclusive routes comprising a plurality of railway traffic governing devices, a circuit controller mounted adjacent said diagram at the representation of each point of traffic entrance for said stretch respectively, and each of said circuit controllers having a plurality of circuit closing positions one for each of a plurality of routes which begin at the corresponding point of traffic entrance to said stretch for selectively arranging a plurality of traffic governing devices in the corresponding routes.

4. In combination, a stretch of railway track including a plurality of switches which can be arranged to form a plurality of routes, a rotary circuit controlling device having a plurality of positions around a given axis, and means controlled by said device in said positions for selectively arranging the switches in said plurality of routes.

5. In combination, a stretch of railway track including a plurality of switches which can be arranged to form a plurality of partly inter-inclusive routes, a circuit controlling device having a plurality of positions one for each of said routes, and means controlled by said device when in each of said positions for arranging the switches in a corresponding one of said routes.

6. In combination, a stretch of railway track including a plurality of switches which can be arranged to form a plurality of partly inter-inclusive routes, a signal for governing traffic movements over each of said routes, a circuit controlling device having a plurality of positions one for each of said routes, and means controlled by said device when in each of said positions for arranging the switches in a corresponding one of said routes and for clearing the signal for that route.

7. In combination, a stretch of railway track including a plurality of switches which can be arranged to form a plurality of partly inter-inclusive routes, a circuit controlling device for each point of traffic entrance to said stretch, each of said devices having a plurality of positions one for each of a plurality of said routes which begin at its point of traffic entrance, means controlled by each of said devices when in each of said positions for arranging the switches in a corresponding route, and means controlled by each of said devices when in certain said positions for preventing arrangement of the switches in each of certain other said routes.

8. In combination, a stretch of railway track including a plurality of switches which can be arranged to form a plurality of partly inter-inclusive routes, a circuit controlling device for each point of traffic entrance to said stretch, each

- of said devices having a normal position and a plurality of reverse positions, a plurality of auxiliary control elements for each of said devices each of which elements is controllable by its device when its device is in one of said reverse positions respectively, a master control element for each of said devices each of which master control elements is controlled by its device when its device is in any of said reverse positions, and 10 means controlled by each master control element and by an associated auxiliary control element for arranging the switches in a corresponding one of said routes.
9. In combination, a stretch of railway track 15 including a plurality of switches which can be arranged to form a plurality of partly inter-inclusive routes, a circuit controlling device for each point of traffic entrance to said stretch, each of said devices having a normal position and a plurality 20 of reverse positions, a plurality of auxiliary control elements for each of said devices each of which elements is controllable by its device when its device is in one of said reverse positions respectively, a master control element for each of said devices each of which master control elements is controlled by its device when its device is in any of said reverse positions, means controlled by each master control element and by an associated auxiliary control element for arranging the switches in each of said routes respectively, and means controlled by each control element for preventing arrangement of the switches in each of certain other said routes respectively.
10. In combination, a stretch of railway track 35 including a plurality of switches which can be arranged to form a plurality of partly inter-inclusive routes, a plurality of master control elements, a plurality of auxiliary control elements controlled by each of said master control elements respectively, and means controlled by each of said auxiliary control elements for arranging the switches in each of said routes respectively.
11. In combination, a stretch of railway track 45 including a plurality of switches which can be arranged to form a plurality of partly inter-inclusive routes, a plurality of groups of said routes, a master control element for each of said groups, an auxiliary control element for each of said routes, and means controlled by the associated master control element and by the associated auxiliary control element for arranging the switches in each of said routes respectively.
12. In combination, a stretch of railway track 55 including a plurality of switches which can be arranged to form a plurality of partly inter-inclusive routes, a plurality of groups of said routes, a master control element for each of said groups, an auxiliary control element for each of said routes, means controlled by the associated master control element and by the associated auxiliary control element for arranging the switches in each of said routes respectively, and indication means controlled by said master control elements.
13. In combination, a stretch of railway track 65 including a plurality of switches which can be arranged to form a plurality of partly inter-inclusive routes, a plurality of groups of said routes, a master control element for each of said groups, an auxiliary control element for each of said routes, means controlled by the associated master control element and by the associated auxiliary control element for arranging the switches in each of said routes respectively, and indication means controlled by each of said routes respectively, and indication

tion means controlled by said auxiliary control elements.

14. In combination, a stretch of railway track including a plurality of switches which can be arranged to form a plurality of partly inter-inclusive routes, a plurality of groups of said routes, a master control element for each of said groups, an auxiliary control element for each of said routes, a stick relay for each route having a pick-up and a stick circuit controlled by the associated master control element and by the associated auxiliary control element, and means controlled by said relay for controlling a traffic governing device for the associated route.

15. In combination, a stretch of railway track 15 including a plurality of switches which can be arranged to form a plurality of partly inter-inclusive routes over said stretch, a master route control relay for each point of traffic entrance to said stretch, an auxiliary route control relay 20 for each route over said stretch, means controlled by each master route relay for controlling an auxiliary route relay for each route which begins at the point of entrance with which said master relay is associated, a manually controllable device for each of said auxiliary route relays, means controlled by each manually controllable device for controlling its auxiliary route relay, and means controlled by each auxiliary route relay for arranging the switches of its route.

16. In combination, a stretch of railway track including a plurality of switches which can be arranged to form a plurality of partly inter-inclusive routes, a plurality of groups of said routes, a master control element for each of said 35 groups, an auxiliary control element for each of said routes, a master relay for each of said groups controlled by the associated master control element and by traffic conditions associated with the same group, an auxiliary control relay for each of said routes controlled by the associated master relay and by the associated auxiliary control element, and means controlled by each auxiliary control relay for arranging all the switches of its route.

17. In combination, a stretch of railway track including a plurality of switches which can be arranged to form a plurality of partly inter-inclusive routes, a plurality of groups of said routes, a master control element for each of said groups, an auxiliary control element for each of said routes, a master stick relay for each of said groups each having a pick-up and a stick circuit controlled by the associated master control element and by traffic conditions associated with the same group, and means controlled by each auxiliary control element and by its associated master stick relay for arranging the switches of its route.

18. In combination, a stretch of railway track including a plurality of switches which can be arranged to form a plurality of partly inter-inclusive routes, a plurality of groups of said routes, a master control element for each of said groups, an auxiliary control element for each of said routes, a stick relay for each of said routes having a pickup and a stick circuit one of which is controlled by the associated master control element and the other of which is controlled by the associated auxiliary control element, and means controlled by each of said stick relays for arranging the switches of its route.

19. In combination, a stretch of railway track including a plurality of switches which can be arranged to form a plurality of partly inter-in-

clusive routes, a plurality of groups of said routes, a master control element for each of said groups, an auxiliary control element for each of said routes, a master route relay for each of said groups each controlled by the master control element for the same group and by back contacts of certain other said master route relays, and means controlled by each master control relay and by an associated auxiliary control element for arranging the switches in each of said routes respectively.

20. In combination, a stretch of railway track including a plurality of switches which can be arranged to form a plurality of partly inter-inclusive routes, a plurality of groups of said routes, a master control element for each of said groups, an auxiliary control element for each of said routes, a plurality of master relays one for each of said master control elements, a restoring control element for each of said master relays, a plurality of route relays one for each of said routes, a pick-up circuit for each of said master relays including the associated master control element and back contacts of certain of said route relays and of certain other said master relays, a stick circuit for each of said master relays including its restoring control element, a pick-up circuit for each of said route relays including an auxiliary control element for the same route and a contact of an associated master relay, a stick circuit for each of said route relays including a contact of an associated master relay, and means controlled by each of said route relays for arranging the switches in its route.

25. 21. In combination, a stretch of railway track including a plurality of switches which can be arranged to form a plurality of partly inter-inclusive routes, a plurality of groups of said routes, a master control element for each of said groups, an auxiliary control element for each of said routes, a plurality of master relays one for each of said master control elements, a pick-up circuit for each of said master relays including its master control element, a stick circuit for each of said master relays controlled by traffic conditions, a normal control relay for each of said switches, a reverse control relay for each of said switches, a pick-up circuit for each of said normal and reverse switch control relays including an auxiliary control element or a contact of the master relay for each route which includes the switch in the normal or the reverse position respectively, a stick circuit for each of said normal and reverse switch control relays including a back contact of the reverse or the normal control relay respectively for the same switch, and means controlled by each of said normal and reverse switch control relays for operating its switch to the normal or the reverse position respectively.

30. 22. In combination, a stretch of railway track including a plurality of switches which can be arranged to form a plurality of partly inter-inclusive routes, a plurality of groups of said routes, a master control element for each of said groups, an auxiliary control element for each switch for each route in which the switch is included, a normal control relay for each switch, a reverse control relay for each switch, a pick-up circuit for each normal or reverse switch control relay including an auxiliary control element or a master control element for each route which includes the switch in the normal or the reverse position respectively, a stick circuit for each of said normal and reverse switch

control relays controlled by a master control element for each route for which an auxiliary control element is included in the pick-up circuit for the relay, and means controlled by each normal and each reverse switch control relay for operating its switch to the normal or the reverse position respectively. 5

23. In combination, a stretch of railway track including a switch which is included in each of a plurality of routes, a plurality of groups of said routes, a master control element for each of said groups, an auxiliary control element for each of said routes, a relay for controlling operations of said switch to one of its extreme positions, a second relay for controlling operations of said switch to the other extreme position, a pick-up circuit for said first relay controlled by an auxiliary control element for each route which includes said switch in said first position, a stick circuit for said first relay controlled by the master control element which is associated with each route which includes said switch in said first position, means for controlling said second relay, and means controlled by said first and second relays for operating said switch to 20 25 said first or said second position respectively.

24. In an interlocking system for railroads, a detector section of railroad track including a track switch, means for operating said track switch, a signal for governing the movement of traffic over a route including said track switch, manually operable means for causing said signal to indicate clear or stop, a track relay for said detector section, a stick relay having a pick-up circuit closed in response to an operation of 30 35 said manually operable means and a stick circuit including a front contact of said track relay, a route relay which becomes energized when said manually operable means has been operated to clear the signal and the route governed by the signal is rendered available by the operation of the track switch, a lock relay which when de-energized prevents operation of the track switch, means preventing energization of said lock relay except when the signal indicates stop, and a circuit for clearing said signal controlled by front 40 45 contacts of said route relay, said track relay and said stick relay, and including a contact controlled by said manually operable means.

25. In combination, a track layout comprising 50 a plurality of track sections interconnected by track switches to form different traffic routes, signals for each direction for governing the movement of traffic over said routes, an entrance stick relay for each entrance end of a route through 55 said layout, exit stick relays for the exit ends of the routes through said layout, a manually operable contact for each stick relay, means for energizing the two stick relays for the two ends of a route when the corresponding manually operable contacts are closed momentarily, and means controlled by said two stick relays when energized for establishing the corresponding route through the layout and for clearing the signal for said route for the corresponding direction 60 65 when said route is established.

26. In combination, a track layout comprising a plurality of track sections interconnected by track switches to form different traffic routes, signals for each direction for governing the movement of traffic over said routes, an entrance stick relay for each entrance end of a route through 70 said layout, exit stick relays for the exit ends of the routes through said layout, a manually operable contact for each stick relay, means for ener- 75

gizing the two stick relays for the two ends of a route when the corresponding manually operable contacts are closed momentarily, means controlled by said two stick relays when energized for establishing the corresponding route through the layout and for clearing the signal for said route for the corresponding direction when said route is established, and means for releasing said stick relays when a train governed by said signal 10 enters said route.

27. In combination, a track layout comprising a plurality of track sections interconnected by track switches to form different traffic routes, manually operable contacts for the ends of the routes through the layout, means responsive to the momentary closing of the two contacts for the opposite ends of a route to establish that route through the layout and for determining the direction of traffic movements over that route 15 when established, and means for automatically cancelling the established route when a train enters the first track section of that route.

28. In combination, a track layout comprising a plurality of track sections interconnected by track switches to form different traffic routes, 25 manually operable contacts for the ends of the routes through the layout, means responsive to the momentary closing of the two contacts for the opposite ends of a route to establish that route through the layout, means for maintaining the established route until cancelled, an auxiliary manually operable contact for each route end, and means responsive to an operation of said auxiliary manually operable contact for 30 one end of an established route for cancelling such route.

29. In an interlocking system for railroads, a plurality of traffic routes through a track layout, manually operable contacts for the ends 40 of the routes through the layout, a stick relay for each route, means responsive to the momentary closing of the two manually operable contacts for the opposite ends of a route to energize the corresponding stick relay, means controlled by each stick relay when energized for 45 establishing the corresponding route, and means for releasing such stick relay to cancel the established route.

30. In an interlocking system for railroads, a plurality of traffic routes through a track layout, manually operable contacts for the ends of the routes through the layout, a stick relay for each route, means responsive to the momentary closing of the two manually operable contacts 55 for the opposite ends of a route to energize the corresponding stick relay, means controlled by each stick relay when energized for establishing the corresponding route, and for rendering the stick relays for conflicting routes non-responsive to the operation of their respective manually operable contacts, and traffic controlled means for releasing each energized stick relay to cancel the corresponding route.

31. In an interlocking system for railroads, a plurality of traffic routes through a layout, a signal at the entrance to each route through said layout, a manually controllable stick relay for each signal, manually operable devices for 60 the exit ends of the routes through said layout, and means effective when the manually operable device for the exit end of a particular route is operated and the stick relay for the signal for such route is also operated for establishing 70 the corresponding route and for automatically 75 clearing the signal for such route when established.

32. In combination, a track layout comprising a plurality of track sections interconnected by track switches to form different traffic routes, a signal at the entrance to each route through said layout, a manually controllable stick relay for each signal, manually operable devices for the exit ends of the routes through said layout, means effective when the manually operable device for the exit end of a particular route is 10 operated and the stick relay for the signal for such route is also operated for operating the track switches of the route as required to establish the route, and means for automatically clearing such signal when the route is fully established.

33. In combination, a track layout comprising a plurality of track sections interconnected by track switches to form different traffic routes, 20 a signal at the entrance to each route through said layout, a manually controllable stick relay for each signal, manually operable devices for the exit ends of the routes through said layout, means effective when the manually operable device for the exit end of a particular route is operated and the stick relay for the signal for such route is also operated for operating the track switches of the route as required to establish the route, and means controlled jointly by 30 said stick relay and manually operable device for clearing the signal for said route when said route is fully established.

34. In an interlocking system for railroads, a plurality of traffic routes through a track layout, a manually operable entrance control element and a manually operable exit control element for each traffic route through said layout, means controlled jointly by the entrance control element and the exit control element for 40 a particular route through the layout for establishing such route, and means independent of said elements for maintaining such route established until cancelled.

35. In combination, a track layout comprising a plurality of track sections interconnected by track switches to form different traffic routes, a switch control relay for each switch of said layout, a manually controllable stick relay for each entrance end of a route through said layout, manually operable contacts for the exit ends of the routes through said layout, means effective when the manually operable contact for the exit end of a particular route is operated and the stick relay for the entrance end of said route 50 is also operated to energize the switch control relay for each switch of the route to establish said route, and means controlled by the stick relay for the entrance end of said route for holding said switch control relays energized to 55 maintain said route established until cancelled.

36. In an interlocking system for railroads, a track layout containing a plurality of track switches to form a plurality of routes, signals for governing traffic movements over said routes, a control device for each end of each route, and means responsive to a signal joint actuation of the control devices for the two opposite ends of a route for operating said switches to the positions required for the route and for automatically clearing said signal for such route.

37. In an interlocking system for railroads, a plurality of routes through a track layout, signals for governing traffic movements over said routes, a route device for each route, route buttons for the 75

two opposite ends of each route, means responsive to the joint operation of said route buttons for the two opposite ends of a route for energizing the route device for that route, and means controlled by such route device for automatically setting up that route through said track layout and clearing said signal for that route.

38. In an interlocking system for railroads, a track layout forming a plurality of routes with each route including a plurality of track switches, signals for governing traffic over said routes, control devices for the ends of said routes, each biased to a normal position, means responsive to the momentary operation of the two control devices for the opposite ends of any route to control all of the track switches in that route to proper positions for the passage of traffic over such route, and other means responsive to said momentary operation of the two control devices for the opposite ends of any route to clear said signal for that route when all of the track switches in that route are in proper positions for such passage of traffic over that route.

39. In an interlocking system for railroads, a single track switch, operable to normal and reverse positions, signals for governing traffic over said track switch in each of its positions in opposite directions whereby any one of four routes may be set up, route devices for the ends of the routes, electroresponsive means responsive to the joint operation of said route devices for the opposite ends of any route for automatically operating said track switch to a proper normal or reverse position for that route and for selecting the direction for traffic movements over that route, and means controlled by said electroresponsive means for clearing said signal for the selected traffic direction when the track switch assumes the position corresponding to that route.

40. In an interlocking system for railroads; a track layout forming a plurality of routes with each route including a plurality of track switches operable to normal and reverse positions; route devices for the ends of said routes each of said devices having a normal position and a control position; and means rendered effective in response to only a momentary operation of said route devices to control positions for the opposite ends of any route to operate said track switches to normal and reverse positions as required by that route.

41. In an interlocking system for railroads, a plurality of routes through a track layout, signals for governing traffic movements over said routes, route devices for the two opposite ends of each route, and means responsive only to the joint operation of said route devices for the two opposite ends of any route for automatically setting up that route through said track layout and clearing said signal for that route in response to a single momentary operation of said route devices.

42. In an interlocking system for railroads, a track layout forming a plurality of routes with each route including a plurality of track switches, signals for governing traffic over said routes, control devices for the ends of said routes, means responsive only to the joint cooperation of said control devices for the opposite ends of any route to control all of the track switches in that route to proper positions for the passage of traffic over such route, and other means responsive to said joint cooperation of said control devices for the opposite ends of any route to clear said signal for that route automatically when all of the

track switches in that route are in proper positions for such passage of traffic over that route.

43. In an interlocking system for railroads, a track layout containing a plurality of track switches operable to normal and reverse positions to form a plurality of routes, signals for governing traffic movements over said routes, a control device for each end of each route and having normal and actuated positions, means responsive only to the joint operation to actuated positions of the control devices for the two opposite ends of each one of said routes for operating said switches to normal and reverse positions to establish such route, and means controlled by the track switches for automatically clearing said signal for governing traffic movements over such route when established.

44. A railway switching system, comprising a stretch of railway track including a plurality of track switches capable of arrangement in various combinations to form a plurality of interconnecting routes, a plurality of manually controllable devices including a pair of said devices for each of said routes, each said device being operable independently of the corresponding control device for a conflicting route, and means controlled by each of said pairs of devices and interlocked electrically with apparatus controlled by the pair of said devices for said conflicting route for controlling the arrangement of all the switches in the corresponding route.

45. In an interlocking control system for a plurality of railway tracks interconnected by switches to form a plurality of routes, normally open manually operable entrance and exit contacts and a normally closed manually operable cancelling contact for each route end, an entrance stick relay for each route end, a route stick relay for each route, a pickup and a stick circuit for each entrance stick relay controlled by the manually operable entrance and cancelling contacts respectively for the same route end, a pickup circuit for each route stick relay controlled by the manually operable exit contact for the exit end of its route and by a back contact of the entrance stick relay for the same route end and also by a front contact of the entrance stick relay for the opposite end of the same route, a stick circuit for each route stick relay which is the same as its pickup circuit except that it includes one of its own front contacts in place of said exit contact, and means controlled by said route stick relays for governing traffic movements over said routes.

46. In an interlocking control system for a plurality of railway tracks interconnected by switches to form a plurality of routes, normally open manually operable entrance and exit contacts and a normally closed manually operable cancelling contact for each route end, an entrance stick relay for each route end, a route stick relay for each route, a pickup and a stick circuit for each entrance stick relay controlled by the manually operable entrance and cancelling contacts respectively for the same route end, a pickup circuit for each route stick relay controlled by the manually operable exit contact for the exit end of its route and by a back contact of the entrance stick relay for the same route end and also by a front contact of the entrance stick relay for the opposite end of the same route, a stick circuit for each route stick relay which is the same as its pickup circuit except that it includes one of its own front contacts in place of said exit contact, means controlled by said

route stick relays for governing traffic movements over said routes, and indication means controlled by said entrance stick relays.

47. In an interlocking control system for a plu-

- 5 rality of railway tracks interconnected by switches to form a plurality of routes, normally open manually operable entrance and exit contacts for each route end, a traffic contact for each route end controlled by a train entering its route
- 10 end, an entrance stick relay for each route end, a route relay for each route, a pickup and a stick circuit for each entrance stick relay controlled by the manually operable entrance contact and by the traffic contact respectively for the corre-
- 15 sponding route end, a control circuit for each route relay controlled by the manually operable exit contact for the exit end of its route and by a back contact of the entrance stick relay for the same route end as well as by a front contact
- 20 of the entrance stick relay for the opposite end of the corresponding route, and railway traffic governing apparatus controlled by said route relays.

48. In an interlocking system for railroads, a

- 25 plurality of routes through a track layout, signals for governing traffic movements over said routes, route devices for the two opposite ends of each route, means responsive to the joint operation of said route devices for the two opposite
- 30 ends of a route for automatically setting up that route through said track layout and clearing said signal for governing traffic movements over that route, and means dependent upon only one of said route devices for the opposite ends of a
- 35 route for maintaining such route established and said signal for that route cleared.

49. In an interlocking system for railroads, a railroad track switch operable to normal and re-

- 40 verse positions by power driven means, a stay-where-put relay for controlling the normal and reverse operations of said track switch, a plurality of control devices including one for the facing position and one for each trailing position of said track switch, means operating said
- 45 relay to a normal switch controlling position only upon the joint operation of said control device for the facing position and one of said control devices for one trailing position, and means operating said relay to a reverse switch controlling
- 50 position only upon the joint operation of said control device for the facing position and the other of said control devices for the other trailing position.

50. In an interlocking system for railroads; a

- 55 track layout forming a plurality of routes with each route including a plurality of track switches operable to normal and reverse positions; route control devices for the ends of said routes each of said devices having a normal position and a
- 60 control position; a route relay for each route, and means responsive to the contemporaneous operation of said route control devices for the opposite ends of any route to their control positions to energize the route relay for that route,
- 65 and means controlled by each route relay when energized to operate the track switches in its route to normal and reverse positions as required by that route.

51. In an interlocking system; a track layout

- 70 having track switches so as to form a plurality of inter-inclusive routes; a route circuit for each of said routes; a route relay included in each route circuit and provided with back contact means for preventing the closing of other route
- 75 circuits which correspond to conflicting routes;

route control devices for opposite ends of said route, each device having normal and controlling positions; means for energizing any route circuit only upon the operation of the route control devices for the opposite ends of that route to controlling positions; and means for operating said track switches to normal and reverse positions as required for any route upon the energization of said route relay for that route.

52. In an interlocking system for railroads; 10

- a railroad track switch operable to normal and reverse positions by power driven means; a switch locking relay, control devices for the facing side and each trailing side of said track switch, said control devices having normal and operated positions; switch control means for controlling the operation of said track switch to normal and reverse positions by the power driven means, means for operating said switch control means effective only when said locking relay is energized 20 and requiring the operation of a control device for the facing side and a control device for one trailing side both to their operated positions for causing the operation of said track switch to its normal position, means for operating said switch control means effective only when said locking relay is energized and requiring the operation of a control device for the facing side and a control device for the other trailing side both to their operated positions for causing the operation of said track switch to its reverse position, and means controlled by traffic conditions adjacent said switch for at times releasing said locking relay to prevent the response of said track switch to the operation of said control devices. 30

53. In an interlocking system for railroads; a

- 40 railroad track switch operable to normal and reverse positions by power driven means; control devices for the facing side and each trailing side of said track switch, said control devices having normal and operated positions; a switch control relay having normal and reverse positions for controlling the operation of said track switch to normal and reverse positions by the power driven means, means for operating said switch control relay to its normal position in response to the operation of a control device for the facing side and a control device for one trailing side both to their operated positions for causing the operation of said track switch to its normal position, means for operating said switch control relay to its reverse position in response to the operation of a control device for the facing side and a control device for the other trailing side both to their operated positions for causing the operation of said track switch to its reverse position; and means allowing only one of said devices for the trailing sides of said track switch to be effective, while in its operated position, for causing response of said switch control relay 60 at any one time.

54. In an interlocking system for railroads; a

- 65 railroad track switch operable to normal and reverse positions by power driven means; manually controllable means for the facing side and each trailing side of said track switch, said manually controllable means having normal and operated positions; a polarized switch control relay having normal and reverse positions for governing the operation of said power driven 70 means; a normal switch control relay responsive to the operation of a manually controllable means for the facing side and said manually controllable means for one trailing side both to their operated positions for operating said 75

5 polarized relay to its normal position to cause the operation of said track switch to its normal position; a reverse switch control relay responsive to the operation of a manually controllable means for the facing side and said manually controllable means for the other trailing side both to their operated positions for operating said polarized relay to its reverse position to cause the operation of said track switch to a reverse 10 position; and means for interlocking said normal and reverse switch control relays so as to allow only one or the other of said switch control relays to be effective to govern said polarized relay in the event that all of said manually controllable 15 means are in operated positions.

55. In an interlocking system for railroads; a railroad track switch operable to normal and reverse positions by power driven means; control devices for the facing end and each trailing end 20 of said track switch, said control devices having normal and operated positions; a normal switch control relay and a reverse switch control relay for governing the operation of said power driven means; normal switch control means responsive 25 to the operation of a control device for the facing end and a control device for one trailing end both to their operated positions for energizing said normal switch control relay to cause the operation of said track switch to its normal 30 position; reverse switch control means responsive to the operation of a control device for the facing end and a control device for the other trailing end both to their operated positions for energizing said reverse switch control relay to 35 cause the operation of said track switch to its reverse position, signals for governing traffic over said track switch in both positions and in opposite directions, signal control means responsive to the operation of said control device for the 40 facing end and said control device for said one trailing end both to their operated positions for clearing one of said signals for governing traffic over said track switch in a normal position only when said track switch occupies its normal position and said normal switch control relay is energized, and signal control means responsive to the operation of said control device for the facing end and said control device for said other trailing end both to their operated positions for 45 clearing one of said signals for governing traffic over said track switch in a reverse position only when said track switch occupies its reverse position and said reverse switch control relay is energized.

55. 56. In an interlocking system for railroads, a railroad track switch operable to normal and reverse positions by power driven means; route control means for the facing side of said track switch and provided with a normal and an operated position, said route control means being so constructed as to remain in the position to which it is last operated; a control device for each trailing side of said track switch and provided with normal and operated positions, said devices being so constructed as to automatically return to their normal positions; normal switch control means responsive to the operation of said route control means for the facing side and said control device for one trailing side both to their operated positions for causing the normal operation of said track switch; reverse switch control means responsive to the operation of said route control means for the facing side and said control device for the other trailing side both to their operated positions for causing the reverse

operation of said track switch; means effective to render said normal switch control means dependent only upon said route control means for the facing side in an operated position after such normal switch control means has responded 5 to said route control means for the facing side and said control device for said one trailing side both in operated positions; and means effective to render said reverse switch control means dependent only upon said route control means for the facing side in an operated position after such reverse switch control means has responded 10 to said route control means for the facing side and said control device for said other trailing side both in operated positions. 15

57. In an interlocking system for railroads; a railroad track switch operable to normal and reverse positions by power driven means; route control means for the facing side of said track switch and provided with a normal and an operated position, said route control means being so constructed as to remain in the position to which it is last operated; a control device for each trailing side of said track switch and provided with normal and operated positions, said devices being so constructed as to automatically return to their normal positions; normal switch control means responsive to the operation of said route control means for the facing side and said control device for one trailing side both to their operated positions for causing the normal operation of said track switch; reverse switch control means responsive to the operation of said route control means for the facing side and said control device for the other trailing side both to their operated positions for causing the reverse operation of said track switch; means effective to render said normal switch control means dependent only upon said route control means for the facing side after such normal switch control means has responded to the operation of said route control means for the facing side and said control device for said one trailing side both to their operated positions; means effective to render said reverse switch control means dependent only upon said route control means for the facing side after such reverse switch control means has responded to the operation of said route control means for the facing side and said control device for said other trailing side; signals for governing facing point train movements over said track switch; signal control means effectively conditioned by said normal switch control means to clear one of said signals only after said track switch has completely responded to such normal switch control means; signal control means effectively conditioned by said reverse switch control means to clear another of said signals only after said track switch has completely responded to such reverse switch control means; whereby a signal is caused to be cleared only upon the joint operation of said route control means for the facing side and one or the other of said control devices for the trailing sides; and whereby a signal is maintained cleared wholly dependent upon said route control means for the facing side. 60 65

58. In an interlocking system for railroads, a track layout having a plurality of track switches so arranged as to form a plurality of interinclusive routes, route devices for the opposite ends of 70 said routes each device having normal and operated positions, a route circuit for each of said routes energized by the joint cooperation of the route devices in operated positions for the opposite ends of that route, a route relay included in 75

each route circuit and provided with back contact means for preventing the closing of the remaining route circuits which correspond to conflicting routes, means for operating said track switches to normal and reverse positions as required for any route upon the energization of said route relay for that route, means controlled by said route relay for that route for clearing the signal at the entrance of that route and rendered effective only after all of said track switches in that route are operated to proper positions.

59. In combination; a track layout including a plurality of track switches operable to positions to establish any one of a plurality of routes each 5 including a plurality of track switches; a plurality of route circuits; a switch machine for each track switch; electroresponsive means controlled by a route circuit for when energized controlling all the switch machines for the track 10 switches for that route to the normal or the reverse position as required to establish such route; a control device for each entrance and exit end of said routes, each control device having a normal inactive and an active position; 15 means responsive only to the joint operation to their active positions of both of the control devices for the entrance end and the exit end of a particular route to energize the electro-responsive means for that route and thereby cause 20 all the track switches in that route to assume a position to establish such route; and stick circuit means effective when a route circuit is energized to maintain it energized independently of the restoration of the control device for the exit 25 end of that route to its inactive position.

60. In an interlocking control system for a plurality of railway tracks interconnected to form a plurality of routes, entrance control devices and exit control devices for said routes, means responsive to operation of both the entrance device 40 and the exit device for any one of said routes for directing traffic movements over the corresponding route, an indication device associated with each of said entrance devices, and means responsive to operation of each entrance device 45 alone for energizing the associated indication device.

61. In an interlocking control system for a plurality of railway tracks interconnected to form a plurality of routes, manually controllable entrance devices and manually controllable exit devices for said routes, and means controlled 50 jointly by the manually controllable entrance and exit devices for each route when in a given condition for directing traffic movements over the associated route and for continuing to direct traffic movements over the associated route as long as said entrance and exit devices for the associated route remain in said given condition 55 even though a manually controllable entrance or exit device for any conflicting route is put into said given condition.

62. In an interlocking control system for a plurality of railway tracks interconnected to form a plurality of routes, manually controllable entrance devices and manually controllable exit devices for said routes, and means controlled by the manually controllable entrance and exit devices 60 for each route when in a given condition for directing traffic movements over the associated route and for continuing to direct traffic movements over the associated route as long as said entrance device for the associated route remains in its given condition even though said exit 75 device is removed from its given condition.

63. In an interlocking system for railroads; a track layout having a plurality of track sections interconnected by a plurality of track switches; signals for governing the entrance of traffic into said track sections in both directions; entrance and exit contacts for the ends of said sections, said entrance contacts being of the stay-where-put type, and said exit contacts being of the self-restoring type; normal and reverse control relays for each of said track switches; means responsive 10 to the joint and contemporaneous operation of an entrance contact for one end of a section and an exit contact for the opposite end of that section or some other section interconnected therewith by said track switches to actuate a normal 15 or a reverse control relay for each of the track switches between said one end and said opposite end; means for causing the normal or reverse operation of each track switch when its corresponding normal or reverse control relay is actuated; means effective to clear the signal at said one end dependent upon the continued operation of said entrance contact independently of the said exit contact, and said means being effective only when all of said track switches are in positions corresponding to the positions required by their respective normal and reverse control relays. 20

64. In an interlocking system for railroads; a track layout having a plurality of track sections interconnected by a plurality of track switches; signals for governing the entrance of traffic into said track sections in both directions; entrance and exit buttons for the ends of said sections, said entrance buttons being of the stay-where-put type, and said exit buttons being of the self-restoring type; normal and reverse switch control relays for each of said track switches, said control relays being so interlocked that only a normal or a reverse relay can be picked up at 30 a time; means responsive to the joint and contemporaneous operation of an entrance button for one end of a section and an exit button for the opposite end of that section or some other section interconnected therewith by said track switches to actuate a normal or a reverse control 35 relay for each of the track switches between said entrance point and said exit point only providing that the control relay for the opposite position is deenergized for each of such track switches, whereby a route is established; means for causing the normal or reverse operation of each track switch when its corresponding normal or reverse control relay is actuated; means effective to clear the signal at the entrance end for which an entrance button is operated wholly dependent upon 40 the maintaining of said entrance button in an operated position independently of the exit button which caused the establishment of the route and effective only when all of said track switches are in positions corresponding to the positions required by their respective normal and reverse control 45 relays. 50

65. In an interlocking system for railroads, a plurality of routes through a track layout having track sections with interconnecting track switches and with signals governing the passage of traffic over such routes, a stay-where-put rotary type entrance contact for the entrance end of each route, a self-restoring exit contact for the end of each route, means responsive only to the joint operation of an entrance contact for one end of a route and an exit contact for the opposite end of that route to automatically establish a route between such points by operating the required track switches to normal and/or reverse 70 75

positions and clearing a signal for that route, and means for maintaining a route established dependent upon the operated entrance contact for that route, whereby the direction of traffic through a route is determined by the combination of entrance and exit contacts operated to establish that route, and whereby only an entrance contact is required to remain in its operated position to maintain a route in an established condition.

66. In an interlocking system for railroads, a route through a track layout, a signal for each end of said route to thereby govern traffic in opposite directions, an entrance button for each end of said route, an exit button for each end of said route operable independently of the entrance button for the same end, said entrance and said exit buttons being constructed differently to be readily distinguishable, and route control means for clearing said signal at one end in response to only the actuation of the entrance button for that end and the exit button for the opposite end and for clearing said signal at the other end in response to only the actuation of the entrance button for that opposite end and the exit button for said one end.

67. In an interlocking system for railroads, a plurality of routes through a track layout having track sections interconnected with track switches and having signals governing traffic over such routes, a route relay for each of said routes, circuit means controlled by each of said route relays for concurrently operating all of the track switches for that route corresponding to such relay, signal clearing circuits for each signal, one circuit for each route over which said signal governs train movement, said signal clearing circuits including contacts of corresponding route relays, whereby a signal is cleared for a given route only if all of the track switches have completely operated to the proper positions for that route.

68. In an interlocking system for railroads, a plurality of routes through a track layout having track sections with interconnecting track switches and with signals governing the entrance of traffic into such routes in both directions, a rotary entrance button for the entrance signal location for each route, exit buttons of the push button type for the exit ends of said routes, and means responsive only to the joint operation of an entrance button for one end of a route and an exit button for the opposite end of that route to automatically establish that route by operating the required track switches to normal and/or reverse positions and clearing a signal at that end of the established route corresponding to said operated entrance button, whereby the direction of traffic through a route is determined by the combination of entrance and exit buttons operated to establish such route.

69. In an interlocking system of the entrance-exit type, a stretch of trackway including at least one track switch, a high-speed signal and a call-on signal for governing traffic over said stretch of track, manually operable control buttons associated with the opposite ends of said stretch of track with the button for the entrance to said stretch having at least two distinctive operated positions, electro-responsive means controlled by the joint operation of said buttons for governing the position of the track switch in said stretch, and electroresponsive means controlled by the joint actuation of said buttons in accordance with the distinctive operation of the button at

the entrance to said stretch for selectively clearing said high-speed signal or said call-on signal.

70. In a system for governing the track switches and signals of a railway track layout, a control machine having a control panel with said track layout represented thereon by a miniature track portion for each corresponding portion of the actual track, rotary stay-where-put entrance buttons located on said panel at the opposite ends of each miniature track portion, self-restoring exit push buttons for the opposite ends of each miniature track portion, electro-responsive means individually associated with each of said track portions and energized in response to only the operation of the entrance button at one end of its miniature track portion and the contemporaneous momentary operation of the exit button for the opposite end of its miniature track portion, circuit means for each of said electro-responsive means effective to maintain its electro-responsive means energized dependent upon said operated entrance button irrespective of the self-restoration of said operated exit button, and means controlled by the said electro-responsive means for each track portion for operating the track switch in that portion and clearing a signal for allowing the passage of traffic thereover.

71. In a system of switch and signal control, a track layout having an arrangement of track switches to provide at least two non-conflicting routes with a conflicting route common to both of said non-conflicting routes, signals for governing traffic over said routes, a control machine having a control panel, manually operable buttons on said control panel for the ends of said routes, route establishing means for each of said routes responsive to the joint operation of said buttons for the opposite ends of such route, switch control means for each of said track switches, means controlled by each of said route establishing means to actuate those of said switch control means required to set up the corresponding route, other means controlled by each of said route establishing means for said non-conflicting routes to actuate that one of said switch control means required to set up the other of said non-conflicting routes in part so as to protect that one of said non-conflicting routes completely set up, and signal control means individual to each of said routes and controlled by said route establishing means for that route to clear a signal for such route only after it has been completely set up and locked.

72. In a system of the character described for a railway track layout having a portion of track with signals at the opposite end of such portion to govern traffic in opposite directions and having intervening turn out track switches, a control machine having a miniature track diagram of said portion of track, entrance buttons on said track diagram at the points on said diagram corresponding to the signal locations of the actual track layout, exit buttons on said track diagram associated with said entrance buttons but being different in appearance so as to be readily distinguishable from their associated entrance buttons, and route establishing means for controlling said track switches to set up a route over said track portion and for clearing said signal at one end of the track portion in response to only the actuation of said entrance button for that end and said exit button for the opposite end, and for controlling said track switches to set up said route over said track portion but for

clearing said signal at the other end in response to only the actuation of said entrance button for such other end and the exit button for said one end.

- 5 73. In a system of the character described for a railway track layout having a portion of track with signals at the opposite end of such portion to govern traffic in opposite directions and having intermediate turn out track switches, a control machine having a miniature track diagram of said portion of track, a rotatable entrance button on said track diagram at each point on said diagram corresponding to a signal location of the actual track layout, a self-restoring exit button 10 15 ton of the push button type on said track diagram associated with each of said entrance buttons but being different in appearance so as to be readily distinguishable from such associated entrance buttons, and route establishing means for controlling said track switches and for clearing said signal at one end of the track portion in response to only the actuation of said entrance button for said one end and said exit button for the other end, and for controlling said track 20 25 switches and for clearing said signal at the other end in response to only the actuation of said entrance button for such other end and the exit button for said one end.

74. In a traffic controlling system for railroads; 30 a power-operated track switch; a detector track section associated with said track switch; a signal for governing traffic over said track switch; a manually operable control switch having a normal position and a plurality of operated positions, said switch having a first contact closed only when said switch is in one operated position, a second contact closed when said switch is in said one operated position or in said normal position and opened only when said switch 35 40 is in another operated position; a neutral relay; a pick-up circuit including said first contact for energizing said neutral relay whenever said switch is in said one operated position, a stick circuit including said second contact for maintaining said neutral relay energized when said button is in said normal position but is deenergized when said switch is in said another operated position; means controlled by said detector track section for opening said stick circuit 45 50 upon the entrance of a train; and means controlled by said neutral relay for governing the clear and stop indications of said signal.

75. In a switch and signal control system of the entrance-exit type, a track layout including a 55 traffic route including one or more power-operated switches and having a main signal and a call-on signal at one entrance end, manually operable buttons for designating the entrance and exit ends of said route, route establishing means 60 responsive to the actuation of said buttons for the exit and entrance ends of said route for operating said track switches to the position required to establish said route and clear said main signal only if said route is not occupied by a 65 train, and means responsive to an additional manipulation of the same button which controls the clearing of said main signal for controlling the clearing of said call-on signal when said route is occupied.

- 70 76. In a switch and signal control system of the entrance-exit type, a track layout including a traffic route including one or more power-operated switches and having a main signal and a call-on signal at one entrance end, manually operable buttons for designating the entrance and 75

exit ends of said route, a clearing circuit for said main signal and a clearing circuit for said call-on signal each controlled in accordance with the position of said switches in said route, said clearing circuit for said main signal also includes contacts opened by the presence of a train in said route, route establishing means responsive to the actuation of said buttons to designate the entrance and exit ends of said route for operating said track switches to establish said route, and relay means responsive to different manipulations of the same button for controlling the clearing circuits of said main signal and said call-on signal respectively. 5 10 15

77. A switch and signal control system for governing power operation of track switches and clearing of signals of a railway track layout including two signals for governing traffic in opposite directions over a route comprising, self-restoring manually operable contacts for designating the entrance and exit ends of said route, an entrance stick relay associated with each signal for controlling the clearing circuit for said signal, a pick-up circuit for each entrance relay normally effective upon actuation of a contact 20 25 for designating the corresponding end of the route as the entrance end to energize that entrance relay, a track circuit controlled stick circuit for maintaining each entrance relay energized until a train passes the corresponding signal, contact means operating in response to the energization of the entrance relay for one of said signals for opening the pick-up circuit of the entrance relay for the opposing signal, an exit relay for each end of said route energized by actuation of a contact for designating the corresponding end of the route as the exit end provided the entrance relay for the opposite end of the route is energized, and route establishing means including said entrance and exit relays 30 35 40 energized in response to the actuation of said manually operable contacts for operating the track switches to set up said route and clear a signal for the end of said route having its entrance relay energized. 45

78. In an interlocking system for railroads, a plurality of routes through a track layout with certain of such routes being non-conflicting, a signal at the entrance of each route, an entrance contact for the entrance end of a route, an exit contact for the exit end of a route, means responsive to the joint operation of the entrance contact and the exit contact for a particular route to operate all the track switches required to set up that route, said means also at the same time operating some other switch not involved in the route thus set up to a position to divert train movement away from said route set up and thereby provide derail protection, and means responsive to said joint operation of said entrance and exit contacts for said particular route to clear said signal for that route after such route has been mechanically set up. 50 55 60 65

79. In a system for controlling the operation of track switches and signals of a railway track layout by the operation of entrance and exit contacts associated with the entering and exit ends of the various routes over said track switches, a plurality of route circuits each individually ap- 70 pertaining to a particular route and closed only by joint manual actuation of the contacts for the entrance and exit ends of said route, means responsive to the energization of a given route circuit for closing a contact for the normal or the reverse position of each of the track switches 75

- in that route to govern the operation of said switches to positions required for that route, switch position detecting means including contacts closed in accordance with the position of each track switch, and a switch correspondence circuit for controlling the clearing of a signal for a given route including contacts operated by the route circuit for that route and contacts operated by the switch position detecting means of the switches of that route, said correspondence circuit being closed only if such route circuit and switch position detecting contacts for all of said switches of the given route are in corresponding positions.
15. 80. In a route interlocking system for controlling traffic movements through a railway track layout comprising track sections interconnected by power operated track switches to form traffic routes with signals for governing traffic movements over said routes, in which the power operation of the switches is governed by locking relays to prevent the operation of each switch of a route when a signal governing traffic movements over such route is at clear and also when
- the route is occupied by a train which is in or approaching the track section containing that switch; the combination of a plurality of route buttons identified with the ends of the routes for selecting the routes, with route relays for establishing the routes; circuit means responsive to only the momentary joint operation of the two buttons for the opposite ends of any desired route, provided no conflicting route has been selected, for energizing certain of said route relays to select such route; means controlled by the energized route relays for operating the track switches to the positions required to establish the selected route and for automatically clearing the signal governing traffic movements over that route when established, and means for automatically releasing said energized route relays when a train enters the first track section of the route, and for also restoring the cleared signal to stop to render the locking of the track switches of the established route dependent only upon the position of said train in said route.
